UNITED STATES PATENT OFFICE.

JAMES L. McQUARRIE, OF OAK PARK, ILLINOIS, AND ALBERT M. BULLARD, OF NEW YORK, N. Y., ASSIGNEES, BY MESNE ASSIGNMENTS, TO WESTERN ELECTRIC COMPANY, INCORPORATED, A CORPORATION OF NEW YORK.

SEMITAUTOMATIC TELEPHONE-EXCHANGE SYSTEM.

Application filed September 27, 1906. Serial No. 336,401.

To all whom it may concern:

Be it known that we, JAMES L. McQUARRIE, of Oak Park, in the county of Cook and State of Illinois, and ALBERT M. BULLARD, of New York, in the county of New York and State of New York, citizens of the United States, have invented a certain new and useful Improvement in Semiautomatic Telephone-Exchange Systems, of which the following is a full, clear, concise, and exact description.

Our invention relates to a telephone exchange system wherein the operator at the central office answers the call of a subscriber in the usual way, by uniting her connecting circuit with such subscriber's line, and mechanical switching mechanism completes the connection by uniting the connecting circuit with the called line. The object of our invention is to lessen the labor of the operators and so to decrease the number of operators required in an exchange, to render it unnecessary to employ trunking operators, and to make possible great speed and precision in establishing connections.

In our system the operator is provided with a sending apparatus which she may set to determine the operation of the said mechanical switching mechanism, to cause the latter to automatically unite her connecting circuit with the proper called line. A number of exchanges may be provided, at each of which a number of telephone lines are centered, trunk lines extending between the exchanges. The operator at each exchange is provided with sending apparatus having keys representing the different offices or exchanges, and decimal digit-keys representing the thousands, hundreds, tens and units digits of subscribers' lines. The operator at an exchange, after answering a call by uniting her connecting circuit with the calling line by means of a connection switch, operates a key representing the office where the line with which connection is desired terminates, which may be the local or a distant office, and also keys representing the digits of the called subscriber's line. The office key selected brings into service mechanism which automatically unites the operator's connecting circuit with an idle trunk line leading to the desired office, and the

digit keys thereupon cause the operation of mechanism at the selected office for uniting said trunk line with the line of the subscriber with whom conversation is desired.

A feature of the invention consists in the arrangement whereby the stepping or operating magnets of the line switching mechanism are caused to operate with the stepping or operating magnets of the sending apparatus by means of pulsating current, the sending apparatus being arranged to cut off such pulsating current from its own magnets and the switching mechanism magnets when the desired connections have been established. The operation of the sending apparatus is controlled by the manipulation of the office and digit keys referred to, which, when once depressed, are locked in such position under the control of release magnets, circuits for said magnets being automatically completed when the switching mechanism has completed the connection of the calling line with the desired line, the entire sending apparatus being at this time automatically restored to normal condition.

Another feature of the invention consists in the provision of a test conductor in association with the line connector, the continuity of this conductor being automatically completed when the connector reaches the terminals of the called line. The said conductor includes a relay which is responsive in case the called line is free to complete the continuity of the talking conductors and dis-associate the local apparatus of the connector therefrom, said relay, in case the called line is busy, being unresponsive and serving to enable a locking circuit to be completed for a test relay, which connects a busy test apparatus with the trunk and connecting circuits, to notify the operator and calling subscriber that the line of the called party is in use. Said busy test apparatus causes a characteristic tone in the operator's telephone, and may also cause a peculiar flashing of the operator's supervisory lamp.

A further feature of the invention consists of the arrangement whereby in case the called party's line is busy when tested, the connector used in establishing the connection will be immediately restored to normal

condition. This may be accomplished by the busy test relay above referred to, which when included in its locking circuit may open the circuit of the retaining magnet of the connector, permitting the restoration of the apparatus thereof to normal condition. The operator upon opening her connection switch in response to the busy signal, effects the automatic restoration of the remaining switching mechanism to normal condition. If the called line is free and connection established therewith, the operator, at the termination of the conversation, in response to the display of the supervisory signals, may open her connection switch, thereby effecting the automatic restoration of all the switching mechanism to normal condition.

Another feature relates to means for associating the operator's sending or controlling device with any one of a plurality of connecting circuits when such connecting circuit is taken for use.

Still another feature of the invention relates to an arrangement of apparatus and circuits by which the final selector or connector has direct access not only to ordinary subscribers' lines, but also to trunk lines, such as those leading to private branch exchanges, and is enabled to discriminate between these two classes of lines in making the busy test, and in associated operations. That is to say, the final selector upon testing a busy line, if it is an ordinary subscriber's line, will automatically transmit a busy signal, and may also restore itself to normal condition; but if the line tested and found busy is one of a group of trunk lines, the selector will automatically proceed to test in rotation the remaining lines of the group, and seize the first one that is free; or if all are busy, the selector after testing the last one of the group will give the busy signal and may restore itself to normal.

We will describe our invention in detail by reference to the accompanying drawings, which represent in diagrammatic form a telephone exchange system embodying our invention, reserving, however, for the appended claims a statement of the parts and combinations which we consider novel with us.

In the drawings—

Figs. 1, 2, 3, 4, 5, 6, and 7 represent an arrangement of circuits and apparatus of a telephone exchange system embodying our invention;

Fig. 8 represents a single-station line leading to terminals upon the connector shown in Fig. 4;

Fig. 9 shows a four-party line with its connector terminals arranged for selective signaling; and

Fig. 10 shows a private branch exchange and its trunk lines and connector terminals.

In tracing the system, the drawings

should be considered in the order of Figs. 7, 6, 5, 1, 2, 3, 4, 8, 9 and 10.

In a system of, for example, 100,000 lines, there may be provided ten offices, at each of which terminate 10,000 lines. At each office the lines may be arranged in groups of 300, although groups of any number might be employed. With such an arrangement there would be 34 groups of 300 lines at each office, or to be exact 33 groups of 300 lines and 1 group of 100. Each connector has a capacity of 300 lines and enough connectors are furnished to handle the calls for each group. The operator in an exchange answers a call in the usual way by uniting her connecting circuit with the line of the calling subscriber, and after ascertaining the number of the called party and the exchange where the line of such party terminates, operates her sending apparatus, depressing the key thereof which represents the desired office, and the thousands, hundreds, tens and units digit keys representing the number of the line wanted. An office stepper forms the terminal of the connecting circuit referred to, and is operated by mechanism controlled by the actuated office key to unite the connecting circuit with an idle trunk line leading to the desired office. Said trunk line terminates at the desired office in a primary selector, which is a machine adapted to select an idle connector belonging to any one of the thirty-four groups.

A translator is provided in connection with the sending outfit to cause the thousands and hundreds keys depressed to operate the primary selector and pick out an idle connector of the group desired. The first 300 lines in the exchange are numbered 0000 to 0299. These numbers would be reached by pressing the "naught" button of the thousands keys and the "1" or "2" button of the hundreds keys. There is a primary controller forming part of the sending outfit, which controls the operation of the primary selector, the two being operated together in series. The translator is provided with three brushes. The first is associated with the thousands and hundreds keys and arranged to stop the translator at a predetermined point to cause the second brush and the primary controller, which are automatically brought into circuit when the translator has stopped, to advance the primary selector into position to connect with the desired connector. The third brush has associated therewith an auxiliary controller and said brush, after the operation of the primary controller, automatically brings into play the auxiliary controller, which advances the brushes of the selected connector to the proper hundreds zone of the three zones of one hundred lines each of such connector. This automatic advance of the selector to the proper zone in non-decimal

steps in response to the actuation of decimally arranged keys relieves the operator of one movement in setting up a connection. The depressed tens and units keys are now brought successively into service, mechanism controlled thereby operating the selected connector to cause the brushes thereof to unite with the terminals of the desired line in the selected zone.

10 We will now describe in detail the circuits and apparatus employed in connecting the subscriber No. 999 shown in Fig. 1, whose line terminates at office "A," with the line of the subscriber No. 1132, shown in Fig. 8, whose line terminates at exchange "B."

The line of subscriber No. 999, Fig. 1, extends in two limbs 1, 2 from the substation to the central office "A," where the line extends through the usual line signal apparatus to the poles of a central battery. At the central office, the usual answering jack 3 is provided for the line, the thimble 4 of said jack being connected with a conductor 5 which leads through the usual cut-off relay to the free pole of a grounded battery 6. The operator is provided with an answering plug 7, with which to unite her connecting circuit with the calling line, the plug 7 and jack 3 constituting a manual connection switch.

The link conductors 8, 9 of the operator's connecting circuit lead from the tip 10 and ring 11, respectively, of the answering plug, through the windings of the usual repeating coil, between which is bridged a battery 12 in the usual manner, to the line brushes of an office selector 13, Fig. 2, a supervisory relay being included in link conductor 9 between the battery and the ring of the plug for controlling the usual supervisory signal. The sleeve 14 of the answering plug is connected with a conductor 15 which leads to earth through the winding of a relay 16. Said relay 16, whose circuit 5, 15, is completed upon the closure of the connection-switch, is provided with an armature connected with the free pole of the battery 17, the front contact of said armature being connected with a conductor 18 leading through contacts of the supervisory relays and the supervisory lamps to earth.

A key 19 is provided in association with the conductors 8, 9 of the connecting circuit, adapted, when operated, to connect the operator's telephone set with the link conductors of the connecting circuit, and also to close a pair of contacts, 20, 21, which control the placing of the sending apparatus into condition to serve the connecting circuit. The contact 20 is connected with a conductor 22 which leads through a resistance 23 and springs 24, 25, associated with relay 26, to the free pole of a grounded battery 27, Fig. 5, while the contact 21 is con-

nected with a conductor 28 which leads through the armature 29 and back contact of relay 30, windings of relays 31 and 26, through the armature 32 and back contact of relay 33 to earth. Thus when key 19 is operated, the circuit 22, 28 is completed to operate relays 31 and 26.

Referring first to relay 31, its armature 34 is connected with a conductor 35 which leads through the contacts of a key 36 to conductor 18, said conductor 18 being connected by the armature of relay 16 with the free pole of battery 17. The front contact of the armature 34 of relay 31 is connected with a conductor 37 which leads through the winding 38 of relay 30 to the armature 29 thereof. A locking circuit is now completed for the relays 31 and 26 independent of battery 27, said circuit extending from the free pole of battery 17 by way of conductors 18, 35, armature 34 and front contact of relay 31, winding 38 of relay 30 to conductor 28, thence through the relays 31 and 26 to earth. The armature 29 of relay 30 is now operated and disconnects the key 19 from the circuit of the magnets 31, 26, so that the operator may at any subsequent time during the process of establishing the connection, or during the connection, listen in on the circuit without interfering with the sending apparatus. The resistance 23 in conductor 22 is for the purpose of preventing a short-circuit of the relay 30 when the armature 34 of relay 31 closes the branch through winding 38 of relay 30 from battery 17.

The relay 31 is also provided with armatures 39, 40. The armature 39 is connected with a common wire 41 leading to the sending apparatus, and said armature is adapted when attracted to engage the member 42 of a pair of normally closed springs 42, 43, included in the strand 8 of the connecting circuit, to separate said springs, the spring 42 being connected with the portion of the conductor 8 leading to the office selector. In like manner, the armature 40 is connected with a common wire 44 leading to the sending apparatus, said armature being adapted to engage the member 45 of a pair of springs 45, 46, which are normally included in the ring strand 9 of the connecting circuit, to separate said springs, the spring 45 being connected with the portion of the strand 9 leading to the office selector. Armatures 39, 40, therefore, in their attractive movement, connect the strands 8, 9 of the connecting circuit with the common wires 41, 44 leading to the sending apparatus.

The relay 26, Fig. 5, in operating attracts its armature 47, which separates the springs 24, 25, included in conductor 22, said armature 47 engaging the spring 25 which is connected with the free pole of grounded bat-

tery 27. The armature 47 is connected with a feed wire 48 which supplies battery to the mechanism of the sending apparatus, and also to a lamp signal 49, which remains displayed while the sending apparatus is in use. The retaining magnets of the sending apparatus are permanently connected with the feed wire 48, and are operated the instant battery is applied by relay 26 to the feed wire. The sending apparatus is now in operative condition to serve the connecting circuit.

Operation of the office selector.

15 The office selector, Fig. 2, is provided with a shaft 50 arranged to have two movements—a rotary movement to select a group of trunk lines leading to a particular office, or as in the present case, a group of trunk 20 lines leading to trunk selectors adapted to select an idle inter-office trunk, and a longitudinal or upward movement to select the first idle trunk line of such group. This shaft carries three brushes, 51, 52, 53, 25 brushes 51 and 52 being connected with the strands 8, 9 of the connecting circuit, and the brush 53 being the local brush. The shaft 50 is adapted to be rotated by means of the magnet 54 and mechanism controlled 30 thereby, and to be moved upward by a magnet 55 and its associated apparatus. The relay 30, Fig. 1, when operated, as before described, serves to place the office selector in condition for operation. The armature 56 of relay 30 is connected with the conductor 57 which leads from conductor 35 and battery 17 through a winding of relay 30, armature 56 and its contact of said relay, contact springs 58, 59 of relay 60 to 35 the office selector, and thence through the winding of a relay 61 and through a pair of contacts 62 closed by the shaft 50 when in normal position, to earth. A circuit for relay 61 is thereby provided by way of conductors 18, 35, 57.

40 The said relay 61 when energized attracts its armatures 63, 64 and 65; the armature 63 being connected with earth and when attracted completing a locking circuit for the relay 61 independent of contacts 62. The armature 65 is connected with the free pole of a grounded battery 67, said armature when attracted engaging its front contact which is connected with a conductor 68 leading 45 to earth through the winding of the retaining magnet 66 of the shaft 50. The armature 64 of said relay is connected with the free pole of battery 67 and the front contact of this armature is connected with a conductor 69 which leads through the contact springs 70, 71, associated with relay 72, through the winding of relay 73 to earth.

45 Relay 73 is provided with two armatures 74, 75, which with their back contacts are normally included in the strands 8, 9, of

the connecting circuit, the armatures being connected directly with the portions of the strands leading to the plug 7. The armature 74 is adapted when attracted to engage a front contact which is connected with the conductor 76 leading through the rotary stepping magnet 54 of the shaft 50, through the contact-springs 77, 78, associated with relay 72, to earth.

50 The armature 75 of relay 73 when attracted is adapted to engage a front contact connected with a conductor 79 which leads through the armature and front contact of retaining magnet 66, relay 72, to earth. The office selector is now in condition for 55 operation.

55 Turning now to the sending apparatus, we will describe the means adapted to be set by the operator to actuate the office selector and select an idle trunk line leading to the exchange where the called party's line terminates. In the present case the selector selects a trunk line which leads to an idle trunk selector, said selector thereupon operating to pick out an idle trunk line leading 60 to the desired office.

65 We will assume that the line of the party with whom conversation is desired terminates at office B, and that his number at said office is 1132. The operator, therefore, after 70 listening in to ascertain the number of the line desired, depresses the office key B, key I of the thousands keys, key I of the hundreds keys, key III of the tens keys, and key II of the units keys.

75 The office controller, Fig. 7, is provided with a series of keys A, B, etc., which are known as the office keys. Each key comprises a plunger adapted when depressed to be locked in such position under the control 80 of a release magnet 80. Each plunger may carry a latch member, preferably conical in form, adapted when the plunger is depressed to engage the under side of a latch bar to lock the plunger in its depressed position, said plunger, when the latch bar is operated by magnet 80 being restored by a suitable spring. Each of said keys, when depressed, forces into electrical contact springs 82, 83, 84. The spring 82 of each key is connected 85 with the feed wire 48 previously referred to, which is connected by relay 26 with the free pole of battery 27. The spring 83 is connected with a conductor 85 which leads to a terminal of a bank of contacts 86 adapted to be engaged by the contact arm 87. Said arm is provided with a stepping magnet 88, the retaining magnet 89 of said contact arm being operated by current from the feed wire 48, as previously described. Said contact arm 87 is connected with a conductor 90 which leads to earth through winding 90 of relay 91.

95 The third spring 84 of each key is connected with a conductor 93 which leads through 100

the winding of relay 94, springs 95, 96, associated therewith, to the ground contact of a pulsator 97, said contact being arranged to be intermittently engaged by the ground-
5 ed spring 98 of said pulsator. The spring 99 of said pulsator is connected with the free pole of grounded battery 100, the contact of said battery spring being connected with a conductor 101 leading to the armature 102 of relay 94. The front contact of said armature 102 is connected with a conductor 103 which leads through the winding of the stepping magnet 88 of contact arm 87, armature 104 and back contact of relay 91,
10 through the armature 105 and back contact of sluggish relay 106 to common wire 41.
15 Assume now that key B has been operated: Current will flow from the feed wire 48 by way of springs 82, 83, to the contact 86^a in the bank 86. Battery will also be applied from the feed wire through the springs 82, 83, 84, to conductor 98 and thence through winding of relay 94, springs 95, 96, of said
20 relay to earth by way of the pulsator when spring 98 thereof engages its contact. When such contact is made, relay 94 is energized to attract its armatures 102, 107. Armature 107 is connected to earth and engages contact spring 95, separating the same from its anvil 96 and completing a locking circuit for relay 94 from the feed wire independent of the pulsator. Armature 102 in its attracted position connects the battery contact of the
25 pulsator with conductors 101, 103. Impulses of current now flow from the free pole of battery 100 over conductors 101, 103, winding of the stepping magnet 88 of contact arm 87, over common wire 41, through armature 39 and spring 42 of relay 31, Fig. 1, to the tip-strand 8, armature 74 of relay 73 of the office selector, Fig. 2, conductor 76, through the stepping magnet 54 of the selector, springs 77, 78 of relay 72 to earth.
30 The pulsator 97, as already described, when in position to close its grounded contact completes a circuit for the relay 94 which connects the battery contact of the pulsator to the stepping magnets. This provision is made so that the first impulse applied to the stepping magnets will be a full one, that is, when the pulsator is engaging its ground contact it completes the circuit for relay 94, so that when it engages its battery contact the circuit for the stepping magnet will be ready to receive the complete impulse.

The stepping magnets 88, 54, respond together to the pulsating current and rotate the contact arm 87 of the controller and the shaft 50 of the selector, respectively. When the contact arm 87 of the office controller reaches the contact point 86^a, which is connected through the key B with the feed-wire, and the shaft 50 has been stepped

around so as to bring its brushes in front of the group of terminals leading to trunk selectors adapted to pick out trunk lines leading to the desired office, current flows from the feed wire through the contact springs 70 82, 83, conductor 85, contact 86^a of the bank 86, contact arm 87, conductor 90, through the winding 92 of relay 91 to earth. Relay 91 is thereby energized and attracts its armature 104, removing pulsating current from the stepping magnets 88, 54. The armature 108 of relay 91 is connected to earth while its front contact is connected with a conductor 109 which leads through the winding 110 of relay 91, winding of sluggish relay 106, to the feed wire. The armature 108 therefore when attracted completes a locking circuit for relay 91, and also the circuit of the sluggish relay 106.

A conductor 111 extends from conductor 90 between the arm 87 and relay 91 to the back contact of armature 112 of sluggish relay 106, said armature 112 being connected with common wire 44, and when the arm 87 reaches the point 86^a at which battery is present, an impulse is delivered before the relay 106 has had time to operate, to conductor 44, from the feed wire, by way of key B, conductors 85, 90 and 111 and the armature 112 and back contact of relay 106. This impulse passes through the armature 40 and its contact 45 of relay 31, Fig. 1, strand 9 of the connecting circuit to the office selector, thence through armature 75 of relay 73 and its front contact to conductor 79, armature and front contact of retaining magnet 66, winding of relay 72 to earth. Relay 72 is thereupon operated and attracts its armatures 113, 114, 115. The armature 114 is connected with conductor 79 105 and is adapted when attracted to engage a contact connected with the conductor 69 which leads to the free pole of battery 67, thereby completing a locking circuit for the relay 72 from the free pole of battery 67, 110 armature 64 of relay 61, conductor 69 to earth by way of armature 114 and conductor 79.

The armature 113 of relay 72 is connected with a conductor 116 which leads to the front contact of armature 117 of relay 73, said armature 117 being connected with a conductor 118 leading to the local brush 53 of the shaft 50. Said armature 113 of relay 72 when attracted engages the spring 71 120 connected directly to earth through relay 73, and connects said relay 73 through its own armature 117 and front contact with the local brush 53, for a purpose to be later explained.

The armature 115 of relay 72 when attracted engages contact spring 78 which is grounded, and separates the same from spring 77, thereby opening the branch 76 containing the stepping magnet 54. Said 130

armature is connected with a conductor which leads through the lifting magnet 55 of the selector, armature 120 and front contact of relay 73, to the battery contact of a 5 pulsator 121. The shaft 50 now begins its upward hunt for a trunk line leading to an idle selector adapted to pick out an idle trunk line leading to the office B. If the first trunk line is busy, battery will be present 10 upon its local terminal 122, and will maintain relay 73 excited in the path provided by way of conductor 118, armature 117 of said relay and its front contact, conductor 116, armature 113 and front contact of relay 72, conductor 69 to earth; the armature 120 of said relay 73 while attracted maintains the circuit of the stepping magnet 55.

When, however, an idle trunk line is 20 reached by the brushes on the shaft 50, there will be no potential present at the local terminal 122 thereof, and the relay 73 will be deprived of current, and will release all its armatures; armature 120 opening the circuit 25 of the lifting magnet 55; armatures 74, 75, restoring the continuity of the strands 8, 9 of the connecting circuit; and the armature 117 breaking the connection of relay 73 with the local brush 53, and connecting at its back 30 contact conductor 118, leading from said brush, with a conductor 123 leading to conductor 69, which is connected by armature 64 of relay 61 with the free pole of battery 67. The brushes 51, 52, 53, of shaft 50, now rest 35 in engagement with contact terminals 124, 125, 122, respectively, connected with a trunk line leading to a trunk selector.

It should be borne in mind that the lowermost set of terminals 122, 125, 124 of the 40 vertical rows forming stopping points for the office selector brushes lead to automatic trunk selectors, otherwise the relay 73 would fail to hold itself operated, after the impulse which energized relay 72 had spent itself. 45 It is also to be assumed that the office selector takes at least one rotary step before engaging the first set.

Operation of trunk selector.

50 The trunk selector comprises a shaft 126 having one movement,—a rotary movement,—said shaft being provided with a stepping magnet 127. The shaft carries three brushes 128, 129, 130; the brushes 128, 129, being line brushes connected by conductor 131, 132, with the contact terminals 124, 125 of the office selector, the armatures 133, 134, and back contacts of a relay 135 being included in said conductors 131, 132, respectively. The local trunk terminal 122 of the selector is connected with the conductor 137 which leads through the retaining magnet 138 of the trunk selector, contacts 139 closed by the selector shaft 126 when in normal po-

sition, winding 140 of relay 135 to earth, 65 current being delivered to said conductor 137 from battery 67, when the brush 53 engages said contact 122 and the relay 73 has restored its armature, as previously described, whereupon the relay 135 and retaining magnet 138 are operated.

The retaining magnet 138 in operating, 70 attracts its armature and completes a locking circuit for itself independent of contacts 139 through its own armature resistance 138^a and ground, the function of this resistance being to prevent the short-circuiting of relay 135. Relay 135 in operating 75 attracts its armatures 133, 134, 141, and 147. The armatures 133, 134, when attracted, 80 maintain the selector brushes 128, 129 dead during the selection. The armature 141 is connected with a conductor 142 which leads through the winding 143 of relay 135 to earth. Said armature 141 in its attracted 85 position engages the contact spring 144, and separates the same from its normal contact 145, said spring 144 being connected with a conductor 146 leading to the local brush 130 upon the selector shaft. The armature 147 90 is connected with a conductor 148 which leads to the battery contact of the pulsator 149, while the front contact of said armature is connected with conductor 150 leading through the winding of the stepping 95 magnet 127 of the trunk selector to earth.

Thus when relay 135 is operated, a circuit is completed by armature 147, by way 100 of conductors 148, 150, said circuit including the magnet 127, which is operated to advance the brush 130 on shaft 126 one step, to the terminals of a trunk line leading to the desired office. If this trunk line is busy, battery will be present at the local terminal 105 151 of such line, and current will flow through the local brush 130, conductor 146, spring 144 and armature 141, conductor 142, winding 143 of relay 135 to earth, maintaining the relay 135 energized. The stepping magnet 127 will thus continue to receive current and will advance the brush another step, and so on until an idle trunk 110 line is found, whereupon current will not be present upon the terminal 151, and relay 135 will be deprived of current, releasing 115 its armatures and restoring the continuity of the talking conductors 131, 132, which were broken during selection to prevent disturbances; opening at armature 147 the circuit of the stepping magnet 127; and breaking at armature 141 the connection of relay 135 with the local brush 130. Spring 145, which now rests in engagement with spring 144, is connected with a conductor 152 leading to conductor 137, which is connected with battery 67, at the office selector, and a potential is thereby applied by way of conductors 69, 123, 118, 137, 152, 146, to the 120 125

contact terminal 151 of the trunk line upon which the selector brush 130 rests, to lock out other trunk selectors from the trunk line selected. The brushes 128, 129 of the 5 trunk selector now rest upon the terminals of the limbs 152, 153, respectively, of a two-wire trunk line leading to the office B and the primary selector forming the terminal of such trunk line at the said distant office.

10 *Operation of translating machine and primary selector.*

As before stated, the line with which connection is desired, is numbered 1132. There- 15 fore the operator depresses key I of the 1000's keys 154, key I of the 100's keys 155, key III of the 10's keys 156, and key II of the units keys 157. The 1000's and 100's keys control the operation of the translator 20 shown at the left in Fig. 6, which operates the primary selector 136, Fig. 3, forming the terminal of the trunk line at the distant office to connect the trunk lines with an idle connector of the group containing the desired number. The shaft 159 of the trans- 25 lator is arranged to have two movements, one in long steps under the control of stepping magnet 160, and the other in short steps under the control of magnet 161. The 30 shaft carries three brushes, the brush 162 being adapted to cooperate with the depressed 1000's and 100's keys, and the bank of contacts 163, to stop the shaft at the proper point to cause the brush 164 of the trans- 35 lator to apply battery to a particular contact of the primary controller 165, and cause the same to operate in series with the primary selector until the contact arm 166 of the primary controller reaches the contact 40 to which battery has been applied by brush 164, and the primary selector reaches the group of trunks leading to the connectors of the group wherein is located the called party's line, at which time the primary controller and primary selector are stopped, 45 and the primary selector caused to locate an idle connector. The third brush 167 of the translator is provided with a bank of contacts 168, which control the application of 50 battery to a predetermined point upon the auxiliary controller 169, which is operated after the primary selector has located the connector to advance the brushes of such connector into the proper bank of its three 55 banks of 100 lines each.

Describing now more in detail the operation of the translating mechanism and primary selector: The relays 511 and 172, Fig. 7, control the starting of the translating mechanism, said relays being arranged to operate when the trunk selector has made connection with an idle trunk line leading to a distant office. Said relay 511 is includ- 60 ed in a conductor 170 leading from the front

contact of the armature 105 of the relay 106, 65 through contact springs 171 controlled by the armature 173 of relay 172, to the feed wire 48, the connection of this conductor at armature 105 of relay 106 with wire 41 being completed when the sluggish relay 106 is 70 operated after the impulse is applied to wire 44 to start the office selector in its upward hunt for an idle trunk selector. The circuit for relay 511 extends from the feed wire 48 through conductor 170 to conductor 41, 75 thence through contacts 39, 42, of relay 31, to link conductor 8, over trunk wire 131 to the trunk selector, through the contacts closed thereby, to trunk wire 152 leading to the distant office, where the same passes 80 through one winding of a repeating coil bridged across the trunk conductors, to a conductor 174, which leads through the winding of relay 175, normally closed contacts 176, 177 of a polarized relay 178, normally closed contacts 179, 180, of said relay, normally closed contacts 181, 182, of relay 183, to trunk conductor 153, and thence to the primary selector, through the armature 184 and back contact of relay 185, to a conductor 186 which leads, through contact springs 187 closed by the shaft of the selector while in normal position.

The relays 511 and 172 of the sending apparatus, Fig. 7, are sluggish in their opera- 95 tion to provide a time interval wherein the primary selector may get into condition for operation. This is accomplished under the control of the relay 175 associated with the trunk line at the distant office, which is in the circuit just traced for the relay 511. Said relay 175 in attracting its armature, completes a circuit for battery 189 by way of conductor 190 which leads through the nor- 100 mally closed contact springs 191, 192 of relay 193, winding of relay 193, winding of the retaining magnet 194 of the primary selector, to earth, through the contact springs closed by the shaft 195 of the primary selector when in normal condition. The relay 193 105 and retaining magnet 194 are now energized and a locking circuit is completed for said relay and magnet independent of relay 175, said circuit extending from the free pole of grounded battery 196, conductor 188, through the contact springs 197, 198 of relay 183, armature 199 of relay 193, (which is now 110 in engagement with the contact spring 191, separating the same from its normal contact 192 and disconnecting battery 189 from the circuit previously traced therefor) through the winding of relay 193, and over conductor 190, through the winding of the retaining magnet and its armature 200 and front contact to earth. The armature 201 of relay 193, which is connected with the portion of conductor 190 leading to the front contact of the armature of relay 175, in its attracted 115 120 125

position opens the contact springs 202 which are normally included in the trunk conductor 152, and engages the member thereof which is connected with the portion of trunk conductor 152 leading directly to the primary selector, the contacts 202 being included in said conductor between the repeating coil and the selector.

The repeating coil serves to maintain the inductive continuity of the trunk circuit while maintaining the circuit broken for direct current. The two windings of the repeating coil connected with the portion of the trunk circuit leading back to the trunk selector are included in a bridge of said trunk conductor with a condenser, while the other two windings of the repeating coil, which are included in the portion of the trunk circuit leading to the selector, are connected in a bridge of the trunk circuit with a grounded battery 203.

The retaining magnet 194 when energized as previously described, attracts its armature 204, completing a circuit from battery 205 by way of conductor 206, through the contact springs 207, 208 of relay 209, winding of relay 185 to earth, said relay thereupon attracting its armatures 210, 184, 211 and 212.

The armature 210 of relay 185, which with its back contact is normally included in the trunk conductor 152, when attracted engages a front contact connected with the conductor 213 leading through the stepping magnet 214 of the primary selector, contact springs 215 of relay 209 to earth. The magnet 214 is arranged to rotate the shaft 195 in thirty-four steps to pick out the group of trunk lines leading to connectors serving a particular group of 300 lines. The remaining armatures of the relay 185 bring into operative condition apparatus which will be hereafter described.

The primary selector is now in condition for operation, and sluggish relay 511 of the sending apparatus, Fig. 7, has now operated to energize relay 172, which in turn causes the deenergization of relay 511, said relay 172 locking itself up, and the combination of relays 511 and 172, with the first-mentioned relay inert and the other energized, starts the translating mechanism. Relay 511 is provided with an armature 216 connected with the feed wire 48, said armature when attracted, completing a circuit for the relay 172. Relay 172, which is also sluggish, attracts its armature 173, opening the contacts 171 which are included in the circuit of the relay 511, and by means of said armature 173 and one of the members of the contacts 171, locking itself to earth from the feed wire. The armature 216 of relay 511, which is connected with the feed wire, is provided with a back contact connected with a conductor 217 leading through the armature 218 and its front contact of relay 172,

to the 1000's keys, and when armature 216 of relay 511 is retracted and armature 218 of relay 172 is attracted, current flows from the feed wire over conductor 217, through the armature 219 and back contact of relay 220 to the 1000's keys 154, Fig. 6.

Each 1000's key, when operated, is arranged to be locked in its depressed position under the control of a release magnet 221, as described in connection with the office controller; each key when depressed forcing into electrical engagement contact springs 222, 223, and 224. Contact-spring 222 is connected with the conductor 217 which is united by the feed wire 48 to the free pole of battery 27, and said spring in engaging its anvil 223 applies battery to a 1000's contact terminal in the bank 163 over which the brush 162 of the translator sweeps. In the present case—calling line 1132—since key I is depressed, battery will be applied to the second 1000's contact point 225 of the bank 163. It will be understood that the brush 162 normally rests one long step from the first terminal which would be "0", or the first 1000's terminal. In the system shown, in order that the brush 162 may reach the second 1000's contact point 225, it is arranged to take three long steps. Between the first and second 1000's contact points there are ten intermediate contacts numbered from "0" to 9 inclusive; and the advance of the brush to any of said intermediate contacts is determined by the 100's keys.

The spring 224 of key I, which is in electrical engagement with springs 223, 222, and thereby with battery 27, is connected with a conductor 226 which extends from all the springs 224 of the 1000's keys, through the winding of relay 227, contact springs 228 associated therewith, to the ground contact of a pulsator 229; and when the ground spring of the pulsator engages said contact a circuit is completed for relay 227 which draws up its grounded armature 230, said armature engaging the member of springs 228 connected with the winding of relay 227 and completing a locking circuit for said relay independent of the pulsator.

The relay 227 is arranged to start the operation of stepping magnet 160 of the translator, said relay having an armature 231, which, when attracted, completes the continuity of a conductor 232 leading from the battery contact of a pulsator 233, through the winding of relay 234, armature 235 and back contact of relay 246 to the conductor 41, which is connected with the tip strand of the connecting circuit, and on through to the primary selector. It will be noted that the locking circuit for relay 227 is established by the pulsator 229 when in engagement with its ground contact, so that the circuit of conductor 232 will be completed before the pulsator 233 engages its battery

contact, thus insuring a complete initial impulse over conductor 232.

When the battery spring of the pulsator 233 engages its contact, current flows over conductor 232 through the relay 234, over conductor 41, tip strand 8, trunk conductors 131, 152, through one winding of the repeating coil to conductor 174, thence through relay 175, contacts of relays 178 and 183, to

10 trunk conductor 153, through the armature 184, and front contact of relay 185, to conductor 237, through contacts 238 of relay 209 to earth through the winding of said relay, this current being without effect upon said 15 relay 209. Relay 175 in the circuit just traced responds to said current, and in attracting its armature applies current from battery 189 to conductor 190, and thence through armature 201 and one of the members 20 of springs 202 of relay 193, to trunk conductor 152, thence through armature 210 and its front contact of relay 185, conductor 213, rotary stepping magnet 214 of the primary selector, contact springs 215 of relay 25 209 to earth, whereupon the stepping magnet 214 is operated to rotate the shaft 195 one step. This advance of the primary selector is simply to save time in the operation of the system.

30 The relay 234 in the circuit traced from the pulsator 233 responds to the pulsations and applies current from battery 239 through the armature 240 and its front contact of said relay 234, to the long step magnet 160 of the translator, which advances the contact arm of the translator in long steps. The relay 234 has an armature 241 also connected with battery 239, said armature when attracted applying current from 40 said battery to a conductor 242 which leads to earth through the stepping magnet 243 of the primary controller 165 to advance the arm 166 thereof.

It will thus be seen that the translator 45 arm, the contact arm of the primary controller, and the contact arm of the primary selector, advance together until the brush 162 of the translator reaches the 1000's point 225 of the bank 163 of contacts, at which 50 time each of said arms will have taken three steps—the translator arm three long steps and the primary controller and primary selector arms three short steps each. The holding or retaining magnets of the translator and primary controller are permanently connected with the feed wire and were operated the instant relay 26 applied battery to the feed wire, when the sending apparatus was taken by the connecting circuit 55 for use.

When the brush 162 of the translator reaches the contact 225 it finds current thereon, and said current passes through the brush 162 to a conductor 244, which leads through the armature 245 and back contact

of relay 220, through the winding 246 of relay 236 to earth operating said relay 236, which opens at its armature 235 and back contact the conductor 232 and the circuit before traced, including the relay 234, pulsator 70 233, and the relay 175 at the primary selector, so stopping the movement of the arms of the translator, primary controller and primary selector.

The translator is now ready to respond 75 to the control of the 100's keys and seek the intermediate point beyond the contact 225 where it is desired to finally stop the translator arm. In the present case, since key I of the 100's keys is depressed, the second intermediate point beyond point 225 80 would be supplied with battery in the following manner:

Relay 236 when energized, as above described, attracts its armature 247, which is 85 connected with a conductor 248 leading through the relay 220 to the feed wire 48. The front contact of armature 247 is connected through a winding of relay 236 to earth; and when said armature 247 is attracted, a circuit is completed for the relay 220 which attracts its armatures 219, 245. Armature 219 when attracted connects conductor 217 and battery 27 with conductor 249 leading to the springs 250 of the 100's 90 keys 155. The armature 245 of relay 220 in its attractive movement connects conductor 244 leading from brush 162 with a conductor 251 leading through the winding of the relay 252 to earth. Brush 162 is now dead, since 100 battery is removed by armature 219 of relay 220 from the thousands keys and so from contact 225.

The three springs of key I of the 100's 105 keys are now in electrical connection (key I being locked in its depressed position under the control of a release magnet 428) and the middle spring 512 applies battery from spring 250, conductors 249, 217, to the second intermediate contact beyond point 225. 110 The third spring 253 applies current by way of the springs 250, 512 and conductors 249, 217, to conductor 254 leading through winding of relay 255, to earth; said relay 255 in attracting its armature completing the 115 continuity of a circuit 513 which extends from the battery contact of a pulsator 257, through the winding of the short step magnet 161 of the translator, through the armature 258 and back contact of relay 252 to earth. The pulsator 257 applies current 120 through the circuit just traced to operate the stepping magnet 161 and advance the shaft in two short steps, until the brush 162 of the translator rests upon the second intermediate point beyond contact 225, at 125 which time current will flow by way of brush 162 and conductor 244, through the armature 245 and front contact of relay 220, conductor 251, to earth through relay 252, which 130

will attract its armature 258 and open the circuit of the pulsator 257 and the stepping magnet 161 of the translator, leaving the shaft of the translator three long steps and 5 two short steps from its normal position.

Primary controller.

The primary controller in an exchange such as we are describing, where the lines 10 are arranged in groups of 300, would have thirty-four contact points, each point representing a "group" contact point of a primary selector, which in like manner would have thirty-four rotary steps to engage thirty- 15 four terminals. From each terminal of the primary controller a conductor runs to three contact points strapped together, over which the second brush 164 of the translator is arranged to sweep, said brush being adapted 20 after the translator has been brought to a predetermined point under the control of the 1000's and 100's keys, to apply battery to a certain group of strapped contacts to stop the controller and selector when the selector is advanced to the group of trunk 25 lines leading to the connectors serving the group of lines in which the called party's line is located. The operation of the primary controller and selector is automatically 30 effected immediately upon the completion of the movement of the translator. The relay 252, which was operated the instant the translator brush 162 landed on the second intermediate point, in attracting its 35 armature 262 applied current from the positive battery 263 to conductor 264 leading to the brush 164, which now rests upon the set of strapped contacts connected with the fourth contact 265 in the bank of contacts 40 of the primary controller 165.

It should be remembered at this point that the primary controller and primary selector brushes on the shaft followed the long steps of the translator brush, so that 45 the arm 166 of the primary controller and the arm 195 of the primary selector now rest on their third "group" terminals. This arrangement is simply to save time in setting up the connection.

50 The armature 266 of relay 252, which was operated when the translator completed its movement, serves to start the primary controller and selector, said armature 266 being connected with a ground contact of the pulsator 267, the front contact of said armature being connected with a conductor 268 leading through contacts 269 and the relay 270 to the feed wire 48. The instant the ground 55 spring of the pulsator 267 engages its contact, a circuit is completed from battery 27 over the feed wire 48, conductor 268, through relay 270, armature 266 and front contact of relay 252, to earth; and the relay 270 in operating attracts its armature 271, 60 which separates springs 269, engaging one

of such springs to complete a locking circuit of such relay 270, from the feed wire independent of the pulsator.

An armature 272 is provided for relay 270, which is connected with the battery contact of a pulsator 273, the front contact of armature 272 being connected with a conductor 274 leading through a relay 275, armature 276 and back contact of relay 277, to conductor 41, which leads to the tip strand 8. Relay 275 controls a circuit from battery 278 through the stepping magnet 243 of the controller. The pulsator 273 applies current through the relay 275 and out over conductor 41, tip strand 8, trunk conductors 131, 152, to the distant office, and thence through conductor 174, relay 175, contacts 181, 182 of relay 183 to trunk conductor 153, thence through conductor 237, and relay 209, to earth, this current, however, not affecting the relay 209. The relay 175 responds to the impulses in the circuit traced and completes a circuit from battery 189 over conductor 190, armature 201 of relay 193, and one of the springs 202 to the trunk conductor 152, thence through the armature 210 of relay 185, conductor 213, stepping magnet 214 of the primary selector, contacts 215 of relay 209 to earth. The relay 275 associated with the primary controller and included in the circuit of pulsator 273 above traced makes and breaks the circuit of the stepping magnet 243 of the controller. The stepping magnets 243 of the controller and 214 of the selector now 100 rotate their respective contact arms until the contact arm 166 of the controller reaches the fourth contact in its path, which is connected by the brush 164 and conductor 264 with positive grounded battery 263, at which point current flows from said battery through the arm 166 of the controller and the conductor 269, leading from said arm through a winding of relay 277, to earth. Relay 277 now operates and attracts its 110 armature 276, opening the circuit from the pulsator 273 through the relay 275 of the primary controller and the relay 175 at the distant station, said relay 175 controlling the circuit through the stepping magnet 214 of the primary selector. Said relay 277 also draws up its armature 280, completing a locking circuit for itself which extends from the feed wire 48 through sluggish relay 281, winding of relay 277 to earth. The brushes on the shaft 195 of the primary selector have now reached the fourth group of trunk lines, which lead to connectors adapted to reach the line with which conversation is desired. 115

Automatic selection of idle trunk by selector.

The attraction of armature 276^a of relay 277 completed the continuity of a conductor 282 which leads from the conductor 269 between the brush 166 and relay 277, 120 125 130

through the armature 276^a and front contact of relay 277, armature 283 and back contact of sluggish relay 281, to conductor 44, and before the sluggish relay 281 has had time to operate, an impulse from positive battery 263 flows by way of conductor 264, brush 164, contact arm 166, and its fourth terminal, conductors 269 and 282, conductor 44, to the ring strand 9 of the connecting circuit, trunk conductors 132, 153, through a lower winding of the repeating coil, to conductor 284, which leads through the contact springs 285, 286, winding of the polarized relay 178 to earth. Said positive current causes the relay 178 to tilt its armature in a contra-clockwise direction, whereupon spring 177 of said relay is separated from its anvil 176 and thrown into engagement with a contact 287 connected with the free pole of grounded battery 288; current thereupon flowing from battery 288 through the springs 287, 177, conductor 174, contacts 181, 182 of relay 183, trunk conductor 153, armature 184 and front contact of relay 185, conductor 237, springs 238 of relay 209, and winding of said relay to earth.

Relay 209 is now energized and draws up its armatures 289, 290, 291. The armature 290 is connected with conductor 206 which leads from the battery 205; and said armature when attracted separates springs 238, engaging the member thereof leading directly to earth through relay 209 and completing a locking circuit for said relay independent of relay 178, which by this time has been deprived of current, owing to the operation of the sluggish relay 281. Armature 291 of relay 209 is connected with a conductor 292 leading through the lifting magnet 293 of the primary selector, armature 212 and front contact of relay 185 to the battery contact of a pulsator 294. And said armature 291 when attracted is adapted to separate springs 215, breaking the continuity of conductor 213 connecting the rotary stepping magnet 214 with trunk conductor 152, and to engage the grounded contact spring of said pair of springs 215 to complete a circuit for the lifting magnet 293 and the pulsator 294. Said magnet 293 is adapted to step the shaft 195 up in search of a trunk line leading to an idle connector adapted to serve the fourth group of three hundred lines in which the line desired, Number 1132, is to be found.

The armature 289 of relay 209 is connected with a conductor 296 leading through the armature 211 and front contact of relay 185 to the local brush 297 of the primary selector; said armature 289 when attracted is adapted to separate springs 207, 208 included in the circuit from battery 205, with relay 185, and to engage the spring 208, which leads directly to earth through relay 185, thereby connecting said relay 185

through its own armature 211 and front contact with said local brush 297.

Now when the selector has been given one upward movement to bring its brushes into engagement with the terminals of a trunk line leading to the first connector of the fourth group, if that connector is busy, the local brush 297 of the trunk line leading to said connector will have potential thereon from the local terminal 298 of such trunk, and current will flow through the local brush 297, conductor 296, armature 211 and front contact of relay 185, winding of relay 185 to earth, maintaining relay 185 energized. Relay 185 in turn will maintain the circuit of the up-stepping magnet 293 intact, and the said magnet 293 will lift the shaft 195 another step, and so on until a trunk line leading to an idle connector is reached, when no current will be found upon the local terminal 298 of such line, and relay 185 will be deprived of current, releasing its armatures. The armatures 210, 212 in retracting restore the continuity of the trunk conductors 152, 153; the armature 212 opens the circuit of the up-stepping magnet 293, and the armature 211 opens the connection of relay 185 with the local brush 297, and engages its back contact connected with a conductor 299 which leads through armature 204 and front contacts of the retaining magnet 194, to the free pole of battery 205, thereby placing by way of local brush 297 a test potential upon the multiples of the local trunk terminal 298.

The line brushes of the shaft 195, which form the terminals of trunk conductors 152, 153, are now in engagement with terminals of the trunk line leading to an idle connector adapted to reach line 1132, said brushes engaging terminals connected with conductors 300, 301, respectively, while the local brush 297, which is connected with the free pole of battery 205, applies battery by way of terminal 298, to the local trunk conductor 302 which leads through the contact springs 303, 304, of a busy test and lock out relay 305 of the selected connector, Fig. 4, through the winding of the retaining magnet 306 of the connector, contact springs closed by the shaft of the connector when in its normal position, to earth. The retaining magnet 306 thereupon attracts its armatures 307^a, 308, armature 307^a completing a locking circuit for the retaining magnet 306, independent of the springs which are separated while the connector shaft is away from normal position.

The auxiliary controller.

After the primary selector has selected an idle connector, the third brush 167, Fig. 6, of the translator and mechanism associated therewith, is arranged to operate the connector to move the brushes on the shaft

thereof into the zone or bank of contacts in which is located the terminals of the called party's line. To this end, in calling line 1132, the auxiliary controller 169 is arranged to cooperate with the brush 167 of the translator to move the brushes of the connector into association with the third bank of contacts, in which is located the terminals of line No. 1132 with which connection is to be established. A conductor 311 leads from the wire 269, which is now supplied with current from positive battery 263 by way of the primary controller, to the brush 167 of the translator which now rests upon a second intermediate contact 310 beyond the second ten's contact of the set or bank of contacts 168, over which the brush 167 sweeps, said second intermediate contact being connected with a conductor 312 which leads to the last contact terminal 313 upon the auxiliary controller 169, said contact 313 being included in a bank of contacts adapted to be engaged by the contact arm 314 of the controller.

The intermediate contact points of the bank 168 are divided into groups of three; the first contact of each group, representing the first zone of a connector, being dead; the second contact, representing the second zone, being connected with conductor 312^a to apply battery to the tenth point of the controller, while the third contact of each group, representing the third zone of a connector is connected with a conductor 312 leading to the twentieth contact of the controller. The auxiliary controller has twenty contacts in its bank, and the contact-arm 314 is arranged to be moved with the connector brushes to place said connector brushes into operative connection with the proper bank of contacts. Thus if the line wanted were in the first bank of contacts, the auxiliary controller would not operate, since the connector brushes are normally in operative relation to said first bank and the brush 167 would rest upon a dead contact. However, if the line desired were in the second bank of contacts, potential would be applied by the translator brush 167 to the tenth contact of the auxiliary controller, and the controller brushes would advance with the connector brushes ten steps, when both brushes and controller arm would be stopped, leaving the connector brushes in operative relation to the second bank. In the present case, in calling line 1132, the twentieth contact 313 would have potential applied thereto by the translator brush 167, and the controller brushes and connector brushes would be advanced until the controller arm reached point 313, and the connector brushes were placed in operative relation to the third bank of contacts, when both brushes and controller arm would be stopped.

Sluggish relay 281 associated with the

primary controller, whose circuit was completed by the armature 280 of relay 277 after the primary controller and primary selector have completed their operation, in operating applies current from negative battery 315 through the armature 316, and front contact of relay 281, through conductor 319, and thence through the winding of relay 317, contact springs 318 thereof, to conductor 41. The circuit of this relay is not completed until the connector selected by the primary selector is in condition for operation, the circuit extending over conductor 41 to the tip strand 8 and thence over trunk conductors 181, 152, through conductor 174, winding of relay 175, to trunk conductor 153, and thence over the conductor 301 to the connector, through springs 320, 321 of a connecting relay 323, to conductor 324, which leads through a resistance 325 to earth through the armature 308 and front contact of the retaining magnet 306, which is now energized. Current in the circuit just traced energizes relay 175, which attracts its armature, applying current from the free pole of battery 189 over conductor 190, through the armature 201 and one of springs 202 of relay 193 to trunk conductor 152, thence through the primary selector, line conductor 300, normally closed contact springs 326, 327 of relay 328, to conductor 329, which leads through the contact springs 330 of a transfer relay 331, rotary stepping magnet 332, to conductor 324, and thence to earth through armature 308, said stepping magnet 332 being energized to give the shaft of the connector an idle movement, which is simply incidental to the operation.

Returning to the auxiliary controller, Fig. 6, relay 317 is now operated by current from battery 315 in the circuit above traced, and attracts its armature 333 which locks relay 317 to earth in a circuit from battery 315 independent of the connector. Relay 317 also attracts its armature 334, which applies current from the positive battery 335 to conductor 336, which leads to the armature 337 of relay 338. Said relay 338 has two windings, one included in a grounded conductor connected with the conductor 312, and the other in a grounded conductor connected with the conductor 312^a, said relay thereby receiving current from the brush 167, when the same rests on either the second or the third contact of a group. In the present case, the brush 167 is resting upon the second intermediate contact past the second 10's point or the third of a group, and current from battery 263 flows by way of conductor 264, brush 164, fourth group of strapped contacts to the fourth contact 265 upon the primary controller, thence by way of arm 166 of the controller, conductors 269 and 311 to the brush 167 of the translator, thence by way of conductor 312,

winding of relay 338 to ground. Relay 338 thereupon attracts its armature, connecting conductor 336 with conductor 339 which leads through the winding of relay 340, contact springs 341 thereof, to the ground contact of a pulsator 342. And when the ground spring of the pulsator 342 engages such contact, a circuit is completed through relay 340, which attracts its armature 343, separating springs 341 and completing a locking circuit for relay 340 from battery 335, independent of the pulsator 342.

The armature 345 of the relay 340 is connected with conductor 41, while the front contact of said armature is connected with a conductor 346 leading through the armature 347 and back contact of the relay 348, winding of the relay 349, to the battery contact of pulsator 342. Current from the pulsator flows through relay 349 to common wire 41, and thence over strand 8, line conductors 131, 152, conductor 174, relay 175, trunk conductor 153, through the selector contacts and over the line conductor 301 to the connector, where the same passes by way of conductor 324 to earth through the armature of the retaining magnet. Relay 175 in said circuit at the selector is now energized, and applies current from battery 189 over conductor 190, and the trunk conductor 152 through the primary selector and line conductor 300, conductor 329 and rotary stepping magnet 332 and conductor 324 to earth.

The shaft 307 is accordingly rotated to locate the bank of contacts in which the called party's line terminates. Relay 349 of the auxiliary controller which is in the circuit traced from the pulsator 342, responds to said pulsating current and makes and breaks a circuit from battery 350 through the stepping magnet 351, of the auxiliary controller, advancing the controller arm with the shaft. When the contact arm 314 reaches the contact terminal 313, to which potential is applied by the brush 167, and the brushes on the connector shaft have advanced to a position one step removed from the third bank of contacts, current flows from battery 263 through the brush 167 of the translator, conductor 312, through the arm 314 of the auxiliary controller, to earth, by way of a conductor 353 which includes the winding of relay 348. Said relay is thereupon energized and attracts its armature 347, breaking the circuit of the pulsator 342, relay 349 of the auxiliary controller, and the relay 175 associated with the primary selector which controls the circuit through the rotary magnet 332 of the connector.

The back contact of armature 337 of relay 338 is connected with a conductor 354 leading to the tens and units keys. It will be understood that when the line desired terminates in the first bank of 100 lines of a con-

nector, the brush 167 after the translator has been operated rests upon a dead contact, and relay 338 does not receive current, so that current from battery 335 is applied directly to the tens and units controller, since the services of the auxiliary controller in such event would not be required.

In the present case, however, the line desired is in the third bank of contacts, and during the operation of the auxiliary controller, current is removed from conductor 354, since the armature 337 of relay 338 is attracted, but when the relay 348 operates, after the connector has been advanced to the proper bank of terminals, current is applied by the armature 355 of relay 348 from wire 353 and battery 263, to a conductor 356 connected with conductor 354, and current flows over conductor 354 through the armature 356 and back contact of relay 357, Fig. 5, to the springs 358 of the tens keys 156 of the tens and units controller.

Tens and units controller.

The tens and units controller is arranged to be set by the operator to be automatically brought into service after the connector has been driven around until its brushes rest one step from the first vertical row of line terminals of the selected bank. In each bank of one hundred lines there are ten vertical rows of ten lines each, and the depressed tens key 156 controls the advance of the connector brushes around to the vertical row which contains the terminal of the line desired, at which time the depressed units key 157 is brought into service to operate mechanism adapted to step the connector brushes up to the desired line terminal.

In calling the line 1132, as before stated, the key III of the tens keys and the key II of the units keys were operated; said keys remaining in their depressed positions under the control of release magnets 359, 360, respectively. The tens and units controller is provided with a bank of contacts provided with tens terminals between which are located intermediate terminals or units terminals, and the brush 361 carried by shaft 362 is arranged to sweep over said terminals; the shaft being advanced in long steps between the tens terminals by a long step magnet 363, and over the intermediate terminals in short steps by magnet 364. A retaining magnet is provided for the shaft 362 receiving current from the feed wire 48, as referred to hereinbefore.

Operation of mechanism controlled by tens keys.

In calling line 1132, key III of the tens keys was depressed and when battery is applied to springs 358, as previously de-

scribed, said spring 358 of key III in engaging spring 365 applies current from battery 263 to the fourth tens terminal of the bank. Spring 365, in engaging its contact 366, applies current from battery 263, to conductor 367, which leads through the winding of relay 368 and contact springs associated with said relay to the ground contact of pulsator 369, and when the ground spring of said pulsator engages its contact, a circuit is completed for relay 368 which draws up its armatures, armature 370 completing a locking circuit for said relay independent of the pulsator.

15 The armature 371 of said relay in its attracted position completes the continuity of a conductor 372 leading from the battery contact of the pulsator 373, through relay 374, armature 375, and back contact of a relay 376, to a common wire 41, and current flows from pulsator 373 over conductors 372, 41, 8, 131, 152, 174, 153, 301, 324 to earth, this circuit including relay 175, which applies current to the rotary stepping magnet 332 of the connector in the circuit formed by conductors 190, 152, 300, 329, 324, said stepping magnet responding to the pulsations and moving the brushes on the shaft 307 of the connector past the vertical rows of terminals in the selected bank. Relay 374 in the circuit traced from pulsator 373, makes and breaks a circuit 376 for the long step magnet 363 of the tens and units controller, which advances the shaft 362 carrying brush 361 in long steps over its bank of contacts. When the brush 361 reaches the fourth tens terminal and the connector brushes have been given four steps and lie below the vertical row of contacts containing the terminals of line 1132, the current which has been applied to the fourth tens terminal of the controller by the depressed tens key III flows over the brush 361, conductor 377 connected therewith, through the armature 378 and back contact of sluggish relay 357, winding 379 of relay 376 to earth. Relay 376 is now operated and attracts its armatures, the armature 375 opening the circuit of the pulsator including the relay 374 of the controller, and the relay 175 of the primary selector which controls the circuit of the rotary magnet of the connector. The armature 380 of relay 376 in its attracted movement completes a locking circuit for the relay 376, said circuit extending from the feed wire 48 through conductor 381, sluggish relay 357, and a winding of relay 376 to earth.

20 The armature 382 of the relay 376 in its attracted movement completes the continuity of the conductor 383 leading from the wire 377, which is connected with the battery through the brush 361, through armature 384 and its back contact of relay 357,

70 to the common wire 44. And before the sluggish relay 357 has had time to operate, an impulse of positive current is applied to the common wire 44, said current flowing from the free pole of grounded positive battery 263, conductors 264, 269, 311, 312, 353, 356, 354, armature 356^a, and back contact of relay 357, through springs 358, 365, of the tens key III, brush 361 of the tens and units controller, conductors 377, 383, 75 armature 382 and front contact of relay 376, and armature 384 and back contact of relay 357, to common wire 44, thence over the line conductors 9, 132, 153, to the distant office, thence over the local wire 284, contact springs 285, 286, of relay 183, through the winding of polarized relay 178 to earth. Said relay thereupon tilts its armature in a contra-clockwise direction, applying current from battery 288, through the springs 287, 177, conductor 174, to the line conductor 153, thence through the primary selector to line conductor 301 and connector, conductor 324, to conductor 387 which leads through contact springs 385, of relay 331, winding of said relay, contact springs 386, of the relay 323, to conductor 324 and earth.

80 The transfer relay 331 is now operated to bring the lifting magnet 388 of the connector into connection with the line conductor 300. The armature 389 of said transfer relay when attracted locks the relay 331 in a circuit over conductor 302, which is connected with the battery 205, conductors 387 and 324, to ground. The armature 389^a of the transfer relay is connected with a conductor 390 which leads through the armature and back contact of a relay 391, winding of the lifting magnet 388 to conductors 387 and 324 and earth. Said armature 389^a when attracted separates contact springs 330, engaging the member thereof connected through conductor 329 and contact springs 326, 327 of relay 328 with line conductor 300. The stepping magnet 388 is now in condition to receive impulses to move the connector shaft 307 upwardly.

Operation of mechanism controlled by units keys.

The sluggish relay 357 above referred to has now been operated, attracting its armatures 384, 356^a, and 378. The armature 356^a, which at this time is connected with positive battery 263, in engaging its front contact applies battery to conductor 392 leading to the main springs 393 of the units keys. Since the key II of the units keys 157 is depressed, its contact spring 393 will rest in electrical engagement with springs 394 and 395, spring 394 being connected with a conductor leading to the third intermediate terminal past the fourth tens terminal of the controller bank of contacts, such termi-

- nal corresponding to the number thirty-two. The spring 395 will apply current from the conductor 392 to the conductor 396 which extends through the winding of relay 397, 5 contact springs associated therewith, to the ground contact of a pulsator 398; and when the ground spring of the pulsator engages said ground contact a circuit will be completed for relay 397, which, in attracting its armature 399, completes a locking circuit for itself independent of the pulsator. Said relay also attracts its armature 400, which completes the continuity of a conductor 401 leading from the battery contact of a pulsator 402, through the winding of a relay 403, armature 404 and back contact of the relay 33, to common wire 41, and as the battery spring of the pulsator 402 intermittently engages its contact, pulsating current 10 will flow over the conductor 401 including relay 403, conductors 41, 8, 131, 152, 174, including relay 175, conductors 153, 301, 324, to earth. Relay 175 will respond to the pulsations in said circuit and apply pulsations 15 from battery 189 by way of conductors 190, 152, 300, 329, 390, 387, 324, to earth, said circuit including the lifting magnet 388 of the connector which gives the connector shaft its upward movement.
- 20 The relay 403 in the circuit of the pulsator 402 intermittently makes and breaks a circuit 406 for the short-step magnet 364 of the tens and units controller, said magnet 364 thereupon advancing the shaft 362 and brush 361 in short steps over the intermediate terminals. When the brush 361 reaches the third intermediate terminal corresponding to units key Number II, and the brushes of the connector have been lifted to the terminal of line Number 1132, current 25 from battery 263 will flow by way of conductors 264, 269, 311, 312, 353, 356, 354, 392, brush 361 of the tens and units controller, conductor 377, to the armature 378 of relay 357, whose front contact is connected with a conductor 407 leading to earth through the winding 408 of the relay 33, which relay thereupon is energized and attracts its armature 404, opening the circuit of the pulsator 402 before traced, including relay 403, and the relay 175 at the distant office which controls the circuit of the lifting magnet of the connector. The shaft of the connector now rests with its brushes in engagement 30 with the terminals of line 1132.
- The armature 32 of said relay 33 in its attractive movement opens the locking circuit including the relay 26 (which applies current from battery 27 to the feed wire 48) and also relay 31, which in releasing its armatures 39, 40, restores the continuity of the link conductors 8, 9, disconnecting therefrom conductors 41, 44, respectively. The armature 405 of the relay 33 is connected 35 with the feed wire 48, the front contact of
- said armature being connected to earth through a winding of relay 33 and with a conductor 409, which leads to the front contact of armature 384 of relay 357, said armature 384 being connected with the wire 70 44. An impulse of negative current from battery 27 is now applied over conductors 48, 409, 383, before the armatures of relays 26 and 31 have been released, said impulse passing over conductors 44, 9, 132, 153, 284, 75 through the polarized relay 178 to earth, and when relay 31 has become inert the supply of negative current for maintaining the actuation of relay 178 is continued from battery 12 in the cord circuit by way of link conductor 9, including armature 504 and normal contacts 46, 45 of relay 31, conductors 132, 153, 284, normal contacts 285, 286 of relay 183 to relay 178 and ground.
- 80 Relay 178 in responding to said negative current tilts its armature in a clockwise direction, and applies current from grounded battery 411 through the springs 412, 180, to conductor 174, and line conductors 153, 301, for the purpose of the busy test to be hereinafter explained. Said armature also closes contact springs 413, 414, applying current from battery 411 to a conductor 415 which leads through a high resistance winding 416 of relay 417, to conductor 174, current from battery 411 finding a path through the winding 416 by way of conductor 174 and line conductors 152, 131 and 8, through the repeating coil associated with the operator's connecting circuit to the grounded pole of battery 12.
- 85 Relay 417 is provided with an armature 418 which, when attracted, completes a circuit from the free pole of battery 196, 90 through the winding of relay 183, conductor 419, to earth; said relay 183 thereupon attracting its armatures 420, 421, 422. The armature 422 is adapted when attracted to separate springs 285, 286, and break the connection of polarized relay 178 with the trunk conductor 153. Said armature is connected with a conductor 423 which leads to the conductor 415, and when said armature is attracted it engages the contact spring 285, 95 100 and includes the winding 416 of the relay 417 in a bridge around the condenser which is included between two windings of the repeating coil, said bridge including conductors 174, 415, winding 416 of said relay 110 105 115 417, conductor 423, armature 422 and contact spring 285 of relay 183, and conductor 284. The winding 416 of relay 417 now receives current in metallic circuit from the battery 12 included in the bridge of the 120 operator's connecting circuit.
- 125 The armature 420 of relay 183 when attracted separates the springs 181, 182, engaging spring 182 to complete the continuity of the portion of trunk conductor 130 135 140 145 150 153 between the repeating coil and the pri-

mary selector; while the armature 421 in its attracted movement separates springs 197, 198, opening the circuit of relay 193, which releases its armatures 201, 199, armature 201 5 permitting the reengagement of springs 202 to complete the continuity of the portion of the trunk conductor 152 extending between the repeating coil and selector, and armature 199 opening at another point the circuit of 10 relay 193. The said armature 421 of relay 183 is adapted when attracted to engage the spring 197, and apply battery 196 to the local wire 190 containing the retaining magnet of the selector, independently of the relay 193, which is now deenergized.

It should be noted at this point that the resistance of the winding 416 of relay 417 in the metallic circuit with the battery 12 at the connecting circuit, is too great to permit 20 the operation of the supervisory relay representing the called line, which accordingly remains inert, maintaining the supervisory signal representing the called line, displayed.

Restoration of sending apparatus.

The relay 26 shortly after the impulse passed from battery 27 over the conductor 44 to operate the relay 417, became deenergized, and retracted its armatures 47, 424, the armature 47 in its retractive movement breaking the connection of battery 27 with the feed wire 48, thereby opening the circuits of the holding magnets of the controllers and translating mechanism, permitting the restoration of the contact arms thereof to normal position. The armature 424 of said relay is connected with the free pole of battery 27, and is adapted during 40 its retractive movement to momentarily make electrical contact with both members of a pair of contacts 426, one member whereof is connected with a conductor 427 leading in multiple branches through the release magnets 80, 221, 428, 359, and 360, respectively of the office, thousands, hundreds, tens and units keys respectively, whereupon the latch bars of said keys are 45 operated and the depressed keys restored to normal position. Current is now removed from all the mechanism of the sending apparatus and the lamp 49 is extinguished, indicating to the operator that the sending apparatus may be taken for use with another connecting circuit if desired.

Test of the called line.

When the polarized relay 178 associated 60 with the primary selector received its impulse of negative current, as above described, it applied current from battery 411, through contact springs 412, 180, conductor 174, contacts 181, 182 of relay 183, before said relay was operated by relay 417, said current 65 passing thence over the line conductors 158,

301, 324, through contact springs 429, closed at the first upward movement of the connector, conductor 430, winding of relay 431, conductors 329, and 324, to ground. The resistance 325 is provided in order to prevent the grounded armature of relay 306 from short-circuiting the transfer relay 331 and to keep relay 431 out of circuit when the impulse is transmitted over the line conductor 301 to operate the transfer relay 331, 75 while still affording a path to ground through relay 175, from the sending apparatus.

The relay 431 responds to the impulse above referred to, and attracts its armature 432, completing the continuity of a test conductor 433, leading from the local brush 434 of the connector shaft, through the connecting relay 323, and relay 391 to conductors 430, 329, 324 and earth.

The telephone line 1132 is shown, Fig. 8, leading in two limbs to its line terminals upon the connector, Fig. 4, its local terminal being connected in multiple to other local terminals representing the said line on other connectors, and to the test thimble of an answering jack, and thence to earth through a battery. Now, in case the line is made busy either at the answering jack of such line, or at a connector making connection with said line, a shunt will be established around the test conductor 433 of another connector attempting to make connection with such line, and the relay 323 will not receive sufficient current for its operation. If, therefore, the line with which connection is desired is busy, after the relay 431 is operated to attract its armatures 432 and 435, and relay 323 fails to respond, current will be applied from a pulsator 436 by way of conductor 437, contact springs 438 controlled by relay 323, through an armature and back contact of relay 391, armature 435 and front contact of relay 431, to earth, through the winding of the busy test and lock-out relay 305, which is sluggish, to provide a time interval wherein the relay 323 may respond if the line is free.

The armature 439 of the relay 305 is connected with the conductor 437, and in its attractive movement separates springs 303, 304, to break the circuit of the retaining magnet of the connector and permit the restoration of said connector to normal condition, said armature engaging the spring 303, which is connected by way of the local conductor 302, and the contacts 297, 298, of the selector, with battery 205, to provide a locking circuit for the relay 305 independent of the apparatus of the connector. The armature 440 is adapted when attracted to complete the continuity of the conductor 441 leading from line conductor 301 to a busy signal apparatus, armature 440 being connected with a vibrating arm adapted to in-

5 intermittently engage a contact connected by conductor 442 to earth, and with a contact connected with a conductor 443 leading through a busy tone apparatus to earth; so
 10 that the busy tone apparatus and ground conductor 442 are alternately applied to the line conductor 301, and so to the ring strand 9 of the connecting circuit, thereby applying a distinctive busy tone to the calling 15 subscriber's telephone set and to the operator's telephone set when she listens in by means of her listening-key.

The intermittent ground applied to the line conductors 301 and 153 is arranged to 20 cause a peculiar flashing of the supervisory signal representing the called line, and this result is accomplished in the following way: The resistance of the winding 416 of relay 417, which is included with the supervisory 25 relay representing the called line in the metallic circuit with the battery 12 at the connecting circuit is too great to permit the energization of the said supervisory relay. Said relay 417 is provided with a low resistance winding 444, included in a shunt 445, about the high resistance winding 416 of said relay, said shunt being controlled by a relay 446 included in the trunk conductor 153 in the path of current from grounded 30 battery 203; and when the ground is applied by the busy test apparatus to the conductors 301, 153, relay 446 is intermittently energized and makes and breaks the shunt 445, including the winding 444, whereupon 35 the supervisory relay of the called line intermittently receives sufficient current to cause the same to vibrate its armature, and the supervisory lamp is caused to give a distinctive signal, indicating to the operator 40 that the called line is busy.

Signaling the called party.

The line conductor 300 normally leads from the primary selector through normally 45 separated contact spring 326 and armature 447 of relay 328, armature 448 and back contact of the ringing relay 449 to the line brush 450 upon the shaft of the connector; while the line conductor 301 leads through 50 the normally separated front contact spring 320 and armature 451 of the connecting relay 323, through the armature 452 and back contact of the ringing relay 449 to the line brush 453. Assume that the line Number 55 1132, with which the connector has united the trunk and the connecting circuits, is free, a circuit will be completed by the local connector contacts leading from the battery associated with the called line, through test conductor 433, connecting relay 323, polarized relay 391 to earth through the armature 432 and front contact of the relay 431, which relay is maintained energized after the relay 183 is excited, through whose normal contacts 181, 182 the initial current from

battery 411 passed, by reason of the contact of armature 420 of relay 183 connected with battery 203 in the trunk circuit, with spring 182, thus substituting battery 203 to maintain an operative circuit for the relay 431. This current in the testing conductor from the battery of the idle called line is sufficient to energize said relay 323, which draws up its armatures 451, 455, and 456. The armature 451 separates springs 320, 321, 75 engaging spring 320 to complete the continuity of line conductor 301, opening the circuits and disconnecting the local apparatus of the connector from the limb 301; the armature 455 is connected with a conductor 457, which leads through the winding of relay 458 to the test conductor 433 between the connecting relay 323 and relay 391; said armature 455 when attracted engages the member of springs 386 which is connected 80 with the portion of conductor 387 leading to the conductor 324 and earth, so that the continuity of the test conductor is maintained independently of the armature 432 of relay 431, current flowing from the battery 90 of the called party's line over the conductor 433 through relay 323, conductors 457, 387 and 324, to earth, maintaining the connecting relay 323 energized. This current also operates relay 458, which is concerned with 95 the selective ringing to be described hereinafter.

The remaining armature 456 of the connecting relay forms the terminal of a conductor 459 leading through contacts 460 of the ringing relay 449, winding of said relay, contacts 461 of relay 328, armature 432 and back contact of relay 431, which is now de-energized, to conductors 430, 329 and 324 and earth. Said armature 456 in its attracted movement separates springs 438, preventing the operation of the busy test apparatus and engaging the member of said springs which leads to the pulsator 436, so that an impulse of current passes from said pulsator 110 over conductors 437, 459, 430, 329, 324 to earth, operating relay 449. Relay 449, in attracting its armature 462, which is connected with battery 463, completes a locking circuit 459, 430, 329, 324, for said relay 449, 115 under the control of springs 461 of relay 328. The armatures 448, 452, with their back contacts are normally included in the line conductors 300, 301, the armatures being connected with the portions of said conductors leading directly to the brushes 450, 453, respectively. 120

The armature 448 of relay 449, when attracted engages a front contact connected with a conductor 464, leading through a 125 winding of a relay 465 to the armature of relay 458, which is now energized, said armature engaging a front contact connected with generator 466 of positive current. The armature 452 of the relay 449 when at- 130

tracted engages its front contact which is connected with the conductor 467 leading through a winding of the relay 465, conductors 329, 324 to earth. Therefore, when 5 the relay 323 operates it completes a locking circuit for relay 449 and ringing current is applied to the line from the free pole of generator 466, conductor 464, winding of relay 465, to the armature 448 and front 10 contact of relay 449, line conductor 300, line brush 450 of the connector, out over a limb of line 1132 and through the bell at the substation, said current returning over the other limb of the line 1132 through brush 15 453 of the connector, and thence over line conductor 301, armature 452 and front contact of relay 449, conductor 467, winding of relay 465 to conductors 329, 324 and earth.

The relay 465 included in the said ringing circuit is not responsive to the current flowing in the circuit above traced, owing to the high resistance of the bell at the substation, but when the called subscriber responds by removing his telephone from its 20 hook, a path of low resistance is established at the substation around the bell, and sufficient current flows in the circuit traced to operate said relay 465. Said relay 465 thereupon attracts its armature 468 which is 25 adapted to complete a circuit leading from the free pole of battery 470 over conductor 469, through the winding of relay 328, conductors 469, 329 and 324 to ground, thereby 30 effecting the operation of relay 328. The armature 471 of relay 328 is connected with 35 said conductor 469 between the relay 328 and armature 468 of relay 465, and when attracted separates springs 461, thereby 40 opening the circuit of the ringing relay 449, which releases its armatures, the armatures 448, and 452 opening the ringing circuit before traced and re-establishing at their back 45 contacts the continuity of the line conductors 300, 301, the armature 462 of the ringing relay in its retractive movement removing the 50 battery 463 from connection with said relay. The armature 471 of the relay 328 engages the member of springs 461 which is 55 connected through the armature 432 of relay 431 and conductors 329, 324 to earth, thereby completing a locking circuit for the relay 328 from battery 470, conductor 469, armature 471 and one of said contacts 461, conductors 430, 329, 324 to earth. The armature 447 of relay 328 in its attractive 60 movement separates contact springs 326, 327, engaging the spring 326 to complete the continuity of line conductor 300.

The called subscriber is now supplied with 65 current for transmission purposes from the battery 203 in the metallic circuit over the trunk and line conductors. Current in this circuit operates relay 446 which establishes the shunt 445 about the high resistance winding of relay 417, said shunt including the

low resistance winding 444 of said relay, whereupon the supervisory relay of the called line associated with the connecting circuit receives sufficient current for its operation, opening the circuit of the supervisory lamp of the called party to extinguish the same. The extinguishment of said lamp informs the operator that the called party has answered. It should be noted at this point that for the automatic signaling of single party lines, relay 458 and its contacts are not needed since conductor 464 may be connected directly with a generator of ringing current. 70 75

The arrangement above described for automatic ringing, forms no part of the present invention, but constitutes the subject-matter of a Patent No. 1,161,608, issued to Albert M. Bullard, November 23, 1915. 80

Restoration of the switching mechanism.

When the conversation is concluded and the subscribers hang up their telephones, the supervisory signals before the operator are displayed, the supervisory relay of the called line being deprived of current by reason of the opening of the shunt 445 about the high resistance winding of the relay 417 controlled by relay 446, which in turn responds to the called subscriber's telephone switch. The operator now removes plug 7 from the answering jack 3 of the calling line, thereby opening the circuit of relay 16 which breaks the circuit of the supervisory lamps, relay 30, and the relay 61 of the office selector, Fig. 2. The relay 61 of the office selector in releasing its armature 63 opens at another point its circuit, and armature 64, in retracting, disconnects battery 67 from wire 69. The armature 65 of said relay 61 in retracting, opens the circuit of the retaining magnet 66, which permits the return movement of the office selector under the control of a suitable spring. Said armature 65 when resting against its back contact connects battery 67 with a conductor 472 which leads through springs 473 closed while the office selector is away from normal position, to the conductor 69, current from battery 67 thereby flowing through the contacts 70, 71 of relay 72, through relay 73 to earth, which thereupon attracts its armatures, opening the link conductors 8, 9, to maintain the brushes 51, 52 dead during the return movement of the office selector, contact springs 473 being opened when the selector reaches normal position to break the circuit above traced for relay 73 and restore the continuity of the link conductors. 90 95 100 105 110 115 120 125

It should be noted at this point that during the return movement of the selector, the relay 61 which controls the placing of the same in condition for operation, is in a circuit open at contacts 62 separated while the selector is away from normal position, and 130

at its armature 63 and front contact, so that the selector cannot be taken for use by the connecting circuit until it has returned to normal position, thus preventing the possibility of an error in setting up a connection.

The attraction of armature 117 of relay 73 of the selector, removes current of the battery 67 from the local brush 53 and local trunk conductor 137 leading to the trunk selector, whereupon its retaining magnet 138 is deprived of current and the trunk selector thereupon restored to normal condition.

It will be noted that during the return movement of the trunk selector the circuit of its retaining magnet 138 is open at two points, namely, the contacts 139 which are open while the selector is away from normal position, and at the armature and front contact of the retaining magnet, so that the trunk selector may not be taken for operation until it has reached normal position.

Turning now to the distant office, the high resistance winding 416 of relay 417 was deprived of current the instant the office selector commenced its return to normal condition. Said relay thereupon retracted its armature and opened the local circuit of relay 183, which restored the normal circuit conditions of the apparatus of the trunk lines and removed current from the retaining magnet 194 of the primary selector, which thereupon released the shaft 195 of the selector, and removed current from the relay 209, permitting it to restore the apparatus of the selector to normal condition and remove current of battery 205 from local brush 297 and local conductor 302 leading to the connector and retaining magnet of said connector. Said retaining magnet of the connector thereupon released its armatures, permitting the restoration of the connector to normal condition.

The armature 308 of the retaining magnet of the connector in retracting opens the locking circuit of relay 328 which thereupon releases its armatures, armature 447 opening the line conductor 300 to maintain brush 450 dead during the return of the connector. In like manner, the brush 453 of the connector is dead during its return movement, since relay 323 is deprived of current the instant the return movement starts, and the armature 451 of said relay 323 in retracting, breaks the continuity of the line conductor 301.

In case the operator desires to take down the connection without removing her answering plug, as where she has commenced to set up a wrong connection and before the relay 183 at the distant office associated with the primary selector has been operated by relay 417, she may operate the key 36, Fig. 1, which breaks the circuit of relays 30, 31 and 61. Relay 31 retracts its armature before relay 61, which is sluggish in recover-

ing, retracts its armatures, so that an impulse of negative current from battery 12 is allowed to flow out through ring strand 9, trunk conductors 132, 153, conductor 284, to earth through the polarized relay 178, 70 which tilts its armature in a clockwise direction, applying a momentary impulse of current from battery 411 through the high resistance winding 416 of relay 417, conductors 174, 152, 131, tip strand 8 to the 75 grounded pole of battery 12. Said relay 417 responds to this momentary impulse and completes a momentary circuit for relay 183, by way of conductors 188, 419, and battery 196, said relay 183, in operating, attracting 80 its armatures to open the locking circuit previously established from battery 196 through relay 193 and the retaining magnet 194 of the primary selector, permitting the restoration of apparatus controlled by relay 193 and the retaining magnet 194 to normal condition, relay 183 thereupon becoming de-energized. The apparatus of the office selector and trunk selector are now restored to normal condition, as previously described, 90 and the operator may proceed to set up a new connection.

Selective signaling of multi-station lines.

Let us now assume that the subscriber with whom conversation is desired is one of a number of parties on the same line, for example, subscriber No. IV on the party line shown in Fig. 9. In said figure are shown the connector terminals of the stations of the party line, it being understood that the brushes carried by the connector before referred to would sweep over said terminals. The operation of selecting proceeds as before described, up to the moment when the connector brushes stop at the terminals representing station No. IV.

The terminal 473 representing station No. I of the party line (which is connected by conductor 474 with the limb 475 of the party line) is connected with a conductor 476, which leads to the terminal 477 of station No. II, terminal 473 of station No. III, to terminal No. 477 of station No. IV. In like manner, the terminal 477 of station No. I (which is connected by a conductor 478 with the limb 479 of the party-line) is also connected to the terminal 473 of station No. II, terminal 477 of station No. III, to terminal 473 of station No. IV.

With this arrangement, it will be seen that opposite terminals of the stations of the party line are connected together. The four local terminals 481 of the stations of the party-line are connected by conductor 482, a resistance 483 being included in said conductor between the terminals 481 of the second and third stations. The conductor 482 is connected with the thimble of the answering jack of the party line and with the free

pole of the battery associated with said line, and the resistance 483 is adapted when placed in series with the testing conductor 433 of a connector to prevent the operation 5 of the relay 458, whose armature normally rests against a contact connected with a negative source of ringing current 484.

When the connector reaches the terminals 477, 473, 481 of station No. IV, contact brush 450 of the connector will rest upon terminal 477, which is connected by conductors 476, 474 with limb 475 of the line, and contact brush 453 of the connector will rest upon terminal 473 which is connected by conductor 478 with limb 479 of the line, and contact brushes 434 of the connector will rest upon terminal 481 which leads through the resistance 483 and conductor 482 to the free pole of battery associated with the 20 called line. Thus when connection is made with terminals of station No. IV of the party line, a circuit will be completed from the free pole of said battery through wire 482, resistance 483, contacts 481, 434, conductor 433, thence through the connecting relay to earth, and upon the operation of the connecting relay through conductor 457 including the marginal relay 458 to earth. The 25 resistance 483 in this circuit will prevent the operation of the marginal relay 458 and, since the connecting relay 323 has operated ringing relay 449 as previously described, ringing current will flow from the free pole of the negative generator 484 through the 30 back contact and armature of relay 458, conductor 464, winding of relay 465, armature 448, and front contact of ringing relay 449, brush 450 of the connector, thence to the terminal 477 of station No. IV, conductors 476, 474, to limb 475 of the line, and thence to earth through the bell at station No. IV. Relay 465 will respond when the called subscriber answers to cut off ringing current as 35 previously described.

If station No. III of the party line were desired, negative ringing current would be applied to limb 479 of the line to operate the bell in said station. If station No. II were desired, the test brush arm resting 40 upon the test terminal of said station would exclude resistance 483 from the circuit of relay 458, said relay thereupon attracting its armature and applying positive current to the limb 475 of the line, to operate the bell at station No. II. In like manner, if station No. I were desired, positive ringing current would be applied to limb 479 of the party line to operate the bell at said station. If the party line were busy the relay 45 45 50 55 60 65

323 would fail to operate and would thereby prevent the application of ringing current to the line and bring about the operation of the lock-out and test relay 305 to inform the operator of the busy condition of the line.

It will be apparent that any selective or code system of ringing or signaling may be embodied in the present system, wherein the test wire is made to do manifold duty in discriminating and in choosing the proper 70 kind of current for selective ringing.

The feature of selective signaling above described forms no part of the present invention, but is described and claimed in the patent to Albert M. Bullard 1,161,608, before mentioned. 75

Calling a private branch exchange.

Private branch exchanges are in practice usually assigned but one telephone number 80 in a directory. That number is always the one ordered by the subscriber. Naturally it is the lowest number of all the lines leading to the private branch exchange. In the present system, advantage has been taken of 85 this fact for convenience in testing such lines. When the connector has advanced its brushes to the first line and after testing the same finds that it is busy, the brushes are automatically stepped ahead to test the next 90 line, and so on until an idle line is reached. Thus there are two functions to be performed by the selecting mechanism, in addition to those described in connection with the single and multi-station lines. These 95 are, first, when the connector reaches the first private branch exchange line, and finds the same busy, it must step automatically ahead to test the next line leading to that private branch exchange, and must continue 100 testing the lines until a free line is found, when it must connect therewith. Second, when calling a private branch exchange, all of whose lines are busy, the connector must progress its test brush over contacts of all 105 the lines until it reaches the terminals of the last line, which must cause it to give the busy signal to the operator as in the case of calling a busy direct line.

The test brush of the connector is advanced to the test terminal of the first trunk line, and finds current of a given polarity which, if such line is busy, operates mechanism to advance the test brush to the next trunk line terminal, and from terminal to 110 terminal until an idle trunk line is reached. When the test brush reaches the last trunk terminal after testing the other trunk lines, it will find current of opposite polarity 115 thereat, which if such last line is busy, will operate mechanism to apply a busy signal to the operator's connecting circuit and effect the automatic restoration of the connector to normal condition.

Let us make connection with a private 125 branch line shown in Fig. 10, which may be the third of a number of trunk lines leading to a private branch exchange No. 1240. The trunk line shown comprises conductors 485, 486, leading from the branch exchange to 130

terminals upon the connector, a local conductor 487 being provided for the trunk line shown, said local conductor leading from the free pole of a positive grounded battery 488 through the usual cut-off relay and answering jack of the trunk line to the local terminal of said trunk line upon the connector. Up to the moment of test, there is no departure from the previous description of the method of operation, but when the test brush 434 reaches the local terminal of the first trunk line it finds instead of negative current, current from a positive battery 488 thereat, which current flows over the test conductor 433 through the relays 323, 391, to earth through the armature 432 of the relay 431. Relay 391 is polarized and responds only to the positive current.

If such first private branch exchange line is already in use, insufficient current will flow through relay 323 to operate the same, for, as already explained, a line is made busy by a shunt to ground from this test terminal formed either by an answering cord or by the grounded test conductor, which a connector places thereat. But there will be sufficient current to actuate the polarized relay 391. The armature 489 of the polarized relay 391 is connected with the pulsator 436, and the front contact of said armature 489 is connected with conductor 490, which leads to conductor 390 through the lifting magnet 388 of the connector, conductors 387, 324, to earth through the armature 308 and front contact of the retaining magnet. The armature 490^a of said relay 391, in its attractive movement, opens the circuit of the stepping magnet 388 leading to the line conductor 300 and to the selector. Under these conditions, the pulsator 436 applies an impulse to the stepping magnet 388 which lifts the shaft 307 to bring its brushes into engagement with the terminals connected with the second trunk line leading to the private branch exchange. If this line is busy, positive current from the battery 488 of the second trunk line will continue to energize relay 391, which will cause the pulsator 436 to operate the stepping magnet 388 and lift the shaft another step to the terminals of the third trunk line, which we will assume to be free, whereupon relay 323 will operate because of the increased flow of current from battery 488, since the trunk line is free, and said relay 323 will open the circuit of the pulsator 436 and cause ringing current to be applied as before described.

During the time of the testing expedition of the connector, the sending apparatus is not in circuit. It is automatically disconnected as soon as the brushes carried by the connector reach the terminal of the first private branch exchange line, as in the case of selecting a single station line, heretofore described.

If all the lines leading to the private branch exchange, No. 1240, had been busy, the connector would have stepped to the terminals of the last trunk line, and would then return to zero and give the busy signal, 70 since the last private branch exchange is connected in the same manner as a subscriber's line, that is, its test terminal is connected with the free pole of a negative grounded battery, which would therefore cause relay 75 391 to retract its armatures, while relay 323 would remain in an inoperative position, such combination of relays effecting the operation of the test and lock-out relay 305.

It will be understood that while a number of batteries are shown throughout the drawings, batteries of the same polarity may be, and usually are, in practice one and the same. In like manner, while a number of pulsators are shown, in practice, pulsators 80 85 having the same speed and voltage may be one and the same.

While we have illustrated and described in detail a system embodying our invention, we do not desire to limit ourselves in any 90 way to the precise circuits and apparatus shown and described, since numerous modifications, alterations and additions may be made in the circuits shown, without departing from our invention. 95

Having thus described our invention what we claim as new and desire to secure by Letters-Patent is:—

1. In a telephone exchange system, the combination with telephone lines extending 100 from substations to a central office, of a plurality of operators' connecting circuits, manually operable means for placing a connecting circuit into service for uniting said connecting circuit with a calling telephone line, 105 an automatic selector individual to each connecting circuit and forming the permanent terminal thereof, an operator's selector-controlling mechanism and means responsive to said first means to associate said mechanism 110 with any of said connecting circuits to cause the selector thereof to unite said connecting circuit with a desired line.

2. In a telephone exchange system, the combination with a telephone line extending 115 from a sub-station to a central office, of other telephone lines extending to other central offices, trunk lines leading from the first-mentioned office to the other offices, a connecting circuit at said first-mentioned office, 120 a manually-operated connection switch for uniting said connecting circuit with a calling line, mechanism forming the terminal of said connecting circuit and controlled by the operator at said first-mentioned office 125 for selecting an idle trunk line leading to one of said central offices and for uniting said connecting circuit therewith, line selecting mechanism associated with said trunk line at the distant office, and mechanism

- adapted to be set by said operator to actuate said selecting mechanism to connect said trunk line with a desired line terminating in said office.
5. The combination with a telephone line extending from a sub-station to a central office, of a connecting-circuit at the central office, a connection-switch for uniting said connecting-circuit with said line, an office selector forming the terminal of said connecting-circuit, trunk lines leading to other central offices, keys representing said offices, and mechanism controlled by a key when depressed for operating said selector to unite said connecting-circuit with a trunk line leading to the office represented by such key.
4. The combination with a telephone line extending from a sub-station to a central office, of a connecting circuit at the central office, a connection-switch for uniting said connecting-circuit with the line, an office selector forming the terminal of said connecting circuit, trunk lines leading from said central office to other central offices, mechanism adapted to be set by the operator to cause said office selector to unite the connecting circuit with an idle trunk line leading to a distant office, a primary selector associated with the trunk line at the distant office, trunk lines leading from said primary selector to line connectors, mechanism adapted to be set by the operator at the first-mentioned central office for operating said primary selector to select an idle connector, and mechanism adapted to be set by the operator at said central office for operating the selected connector to unite said connecting circuit and trunk lines with a desired telephone line.
- 40 5. In a telephone exchange system, the combination with a telephone line extending from a sub-station to a central office, of a connecting-circuit at the central office, a manually-operated connection-switch for uniting said connecting-circuit with said line, mechanical switching mechanism forming the terminal of said connecting circuit, and adapted to unite said connecting-circuit with a telephone line, and means automatically operated in case said line is busy for applying a busy signal to said connecting-circuit.
- 55 6. In a telephone exchange system, the combination with a telephone line extending from a sub-station to a central office, of a connecting-circuit at the central office, a manually operated connection-switch for uniting said connecting-circuit with said telephone line, mechanical switching mechanism forming the terminal of said connecting-circuit, automatic controlling mechanism adapted to be set by the operator to actuate said switching mechanism to unite the connecting-circuit with a desired line, a busy signal, and means automatically operated in case said switching mechanism connects with a called but busy line for applying said busy signal to the connecting-circuit.
7. In a telephone exchange system, the combination with a telephone line extending from a sub-station to a central office, of a connecting-circuit at the central office, a manually operated connection-switch for uniting said connecting circuit with the telephone line, a connector carrying line terminals, a contact-arm for said connector adapted to be electrically united with said connecting-circuit and to sweep over said line terminals, automatic controlling mechanism adapted to be set by the operator to advance said arm to the terminals of the desired line, a busy signal apparatus, and a relay in a circuit completed when connection is made by the connector with a busy called line, said relay operating in case said line is busy to apply said busy signal apparatus to the connecting-circuit.
8. In a telephone exchange system, the combination with a telephone line extending from a sub-station to a central office, of an operator's connecting-circuit at the central office, a manually-operated connection-switch for uniting said connecting-circuit with the line, mechanical switching mechanism adapted to unite said connecting-circuit with the called line, a supervisory signal associated with said connecting-circuit, and means automatically operated in case the called line is busy for causing said supervisory signal to give a characteristic busy signal.
9. In a telephone exchange system, the combination with a telephone line extending from a sub-station to a central office, of an operator's connecting-circuit at the central office, a manually-operated connection-switch for uniting said connecting-circuit with the telephone line, a supervisory signal associated with said connecting-circuit, an operator's telephone arranged to be united with said connecting-circuit, mechanical switching mechanism for uniting said connecting-circuit with a called line, a busy-tone apparatus, and means automatically operated in case said called line is busy for applying said busy-tone apparatus to the operator's telephone, and for causing said supervisory signal to give a characteristic busy indication.
10. In a telephone exchange system, the combination with a telephone line extending from a sub-station to a central office, of a connecting-circuit at the central office, a manually operated connection-switch for uniting said connecting-circuit with said line, mechanical switching mechanism associated with said connecting-circuit, automatic controlling mechanism adapted to be set by the operator to operate said switch-

- ing mechanism and unite the connecting-circuit with the desired line, a supervisory lamp and a local circuit therefor associated with the connecting-circuit, an operator's 5 telephone arranged to be united with the connecting-circuit, a busy-tone apparatus, and means automatically operated when said switching mechanism connects with a busy line for applying said busy-tone apparatus to the operator's connecting-circuit, and for interrupting said local circuit to cause the flashing of said supervisory lamp, to indicate the busy condition of the called line.
- 10 11. In a telephone exchange system, the combination with a telephone line extending from a substation to a central office, of a connecting-circuit at the central office, a connection-switch for uniting said connecting-circuit with the line, mechanical switching mechanism forming the terminal of said connecting circuit and adapted to unite said connecting-circuit with a desired telephone line, a busy signal, means automatically operated when said switching mechanism connects with a busy line for applying said busy signal to the connecting-circuit, and automatic means for restoring said switching mechanism to normal condition.
- 15 12. In a telephone exchange system, the combination with a telephone line extending from a substation to a central office, of an operator's connecting-circuit at the central office, a connection-switch for uniting said connecting-circuit with the telephone line, an automatic connector carrying line terminals, a contact-arm forming the terminal of said connecting circuit and adapted to sweep over said terminals to unite said connecting-circuit with a desired line, automatic controlling mechanism adapted to be set by the operator to advance said arm to the terminals of the desired line, a busy signal, and mechanism automatically operated in case said connector unites with a busy line for applying said busy signal to the connecting-circuit, and for restoring said connector to normal condition.
- 20 13. In a telephone exchange system, the combination with a telephone line extending from a substation to a central office, of a connecting-circuit at the central office, manually operable means for placing a connecting circuit in service for uniting said connecting-circuit with said telephone line, mechanical switching mechanism for uniting said connecting-circuit with another line, sending apparatus adapted to be set by the operator to actuate said mechanism, 25 means responsive to said first means to associate said apparatus with any of said connecting circuits and a key associated with said connecting-circuit controlling the restoration of said switching mechanism to normal condition.
- 25 14. The combination with line switching mechanism, of a talking circuit adapted to be connected by said mechanism with a telephone line, a testing circuit completed when connection is made with a line, a relay in 70 said circuit, a shunt established about said relay in case the line desired is busy, to prevent the operation of said relay, and a busy signal adapted to be applied to said talking circuit upon the closure of said testing circuit and the unresponse of said relay, said relay when responsive completing said talking circuit.
- 30 15. The combination with line switching mechanism, of a talking circuit adapted to 80 be connected by said mechanism with a telephone line, a testing circuit completed at one point by said switching mechanism in uniting with a line, a relay adapted to complete said testing circuit at another point, 85 a circuit for said relay completed when said mechanism connects with said line, a relay in said testing circuit, adapted, when energized, to complete the talking circuit, a shunt about said relay completed by other 90 switching mechanism already connected with the line to prevent the operating of said relay, and a busy signal applied to said talking circuit upon the operation of said first-mentioned relay and unresponse of said 95 second relay.
- 35 16. The combination with line switching mechanism, of a talking circuit adapted to 100 be connected by said mechanism with a telephone line, a testing circuit completed at one point by said switching mechanism in uniting with a line, a relay 431 adapted to complete at another point the continuity of said testing circuit, a circuit for said relay completed when said switching mechanism connects with a line, a relay 323 in said testing circuit adapted when energized to complete 105 the continuity of said talking circuit, a shunt about said relay formed by other switching mechanism already connected with the line, to prevent the operation of said relay, a sluggish relay, a busy-tone apparatus adapted to be connected thereby 110 with said talking circuit, and a circuit for said relay completed upon the operation of relay 431 and the unresponse of relay 323.
- 40 17. The combination with a telephone line, extending from a substation to a central office, of a connecting circuit at the central office, a connection-switch for uniting 115 said connecting circuit with said line, mechanical switching mechanism for uniting said connecting circuit with another telephone line, sending apparatus adapted to be set by the operator to actuate said switching mechanism, a testing circuit completed at one point by said switching mechanism in uniting with a line, a relay 431 adapted to 120 complete said testing circuit at another point, a circuit for said relay controlled by 130

said sending apparatus and completed when the switching mechanism unites with the called line, a relay 323 in said testing circuit adapted when energized to complete the continuity of the circuit between the two lines, a shunt about said relay 323 completed by another switching mechanism already united with the called line, to prevent the operation of relay 323, and a busy signal apparatus applied to said connecting circuit upon the operation of relay 431 and the un-response of relay 323.

18. The combination with a telephone line extending from a substation to a central office, of a connecting circuit at the central office, a manual connection-switch for uniting said connecting circuit with said line, mechanical switching mechanism adapted to unite said connecting circuit with another telephone line, a relay associated with said mechanism, a circuit for said relay completed when said mechanism unites with a desired line, said relay responding in case the line is free, and remaining inert if said line is busy, and a busy signal applied to the connecting circuit by said relay if unresponsive, said relay in responding completing the continuity of said talking circuit.

19. The combination with connectors provided with contact members having line and test terminals adapted to engage corresponding terminals of telephone lines, a talking circuit connected with the line terminals of each connector-member, the terminals of telephone lines being multiplied upon said connectors, a battery having one pole connected with the test terminals of said lines, a testing conductor connected with the test terminal of each connector-member and leading to the other pole of said battery, a relay in each testing conductor, adapted in responding to complete the continuity of the talking circuit of said connector, the testing conductor of a connector united with a line being adapted to form a shunt about the test conductor of another connector attempting to make connection with said line to prevent the operation of the relay of said second connector, and a busy signal applied to the talking circuit of said second connector by said relay if unresponsive.

20. The combination with connectors provided with contact-members having line and test terminals adapted to engage corresponding terminals of telephone lines, of a talking circuit connected with the line terminals of each connector-members, the terminals of said lines being multiplied upon said connectors, a battery having one pole connected with the test terminals of said lines, a testing conductor connected with the test terminal of each connector-members, mechanism associated with each connector actuated when terminals of said connector-members engage the terminals of a desired

line for connecting said testing conductor with the other pole of said battery, a relay in said testing conductor responsive to said battery to complete the continuity of the talking circuit of such connector, the testing conductor of said connector being adapted to form a shunt about the testing conductor of another connector attempting to connect with said line to prevent the operation of the relay in said other test conductor, and a busy signal applied to the talking circuit of said other connector jointly by said mechanism of such other connector and the unresponsive condition of the relay of such connector.

21. The combination with a connector, of a talking circuit therefor, adapted to be connected with a telephone line, mechanism for operating said connector, a relay adapted when energized to complete the continuity of said talking circuit, a circuit for said relay controlled jointly by said mechanism and by said connector after uniting with a desired line, said relay being unresponsive if the called line is busy, a relay, busy-signal apparatus adapted to be applied thereby to said talking circuit, and a circuit for said relay completed jointly by said mechanism and by said first-mentioned relay if unresponsive.

22. The combination with a connector, of a talking circuit therefor, adapted to be connected with a telephone line, mechanism for operating said connector, a relay adapted when energized to complete the continuity of said talking circuit, a circuit for said relay controlled jointly by said mechanism and by said connector after uniting with a desired line, said relay being unresponsive if the called line is busy, a relay, busy-signal apparatus adapted to be applied thereby to said talking circuit, a locking circuit for said relay completed jointly by said mechanism and by said first-mentioned relay if unresponsive means controlled by said second relay for restoring the connector to normal position, and means actuated upon the restoration of the apparatus of the talking circuit to normal condition for opening said locking circuit.

23. The combination with a telephone line extending from a substation to a central office, of a connecting-circuit at the central office, a connection-switch for uniting said connecting-circuit with said line, mechanical switching mechanism forming the terminal of said connecting-circuit, controlling mechanism adapted to be set by the operator for applying pulsating current to operate said controlling mechanism and switching mechanism, and means operated by said controlling mechanism when the switching mechanism connects with a desired line for cutting off said pulsating current.

24. In a telephone exchange system, the

combination with a telephone line extending from a substation to a central office, of a connecting-circuit at the central office, a connection-switch for uniting said connecting-circuit with another telephone line, an automatic connector carrying line terminals, a contact-member arranged to be associated with said connecting circuit and adapted to sweep over said terminals, a keyboard for the operator comprising keys having plungers representing the tens and units digits of the lines in the exchange, means controlled by the plunger representing the tens digit of the called line for advancing said member to the terminal represented by said tens digit, and means controlled by said units plunger for advancing said member to the desired line terminal.

25. In a telephone exchange system, the combination with a telephone line extending from a substation to a central office, of a connecting circuit at the central office, a connection-switch for uniting said connecting-circuit with said line, mechanical switching mechanism adapted to unite said connecting circuit with a desired line, sending apparatus adapted to be set by the operator to apply pulsating current to operate said switching mechanism, and means controlled by said sending apparatus for cutting off said pulsating current when said switching mechanism unites with a desired line.

35. In a telephone exchange system, the combination with a telephone line extending from a substation to a central office, of a connecting circuit at the central office, a connection-switch for uniting said connecting-circuit with said line, mechanical switching mechanism adapted to unite said connecting circuit with a desired line, a source of pulsating current for operating said switching mechanism, and sending apparatus adapted to be set by the operator to apply said pulsating current to the switching mechanism, said sending apparatus being operated by said current in unison with said switching mechanism and arranged to cut off said said pulsating current when the switching mechanism reaches the desired line.

55. In a telephone exchange system, the combination with a telephone line extending from a substation to a central office, of a connecting-circuit at the central office, a connection-switch for uniting said connecting-circuit with the said line, an automatic connector, an operating magnet therefor adapted to cause said connector to unite said connecting-circuit with another line in the exchange, a source of pulsating current adapted to be connected with said magnet to operate the same, and automatic mechanism adapted to be set by the operator to discon-

nect said source of current from said magnet when the connector unites with the desired line.

28. The combination with a line switching device, of a contact-member therefor, an operating magnet for said member, a controller adapted to be set to determine the advance of said member, an operating magnet for the controller, pulsating current adapted to be applied to said magnets on setting the controller, and means automatically operated by the controller when the contact-member has advanced the predetermined distance for cutting off said current.

29. The combination with a line switching device carrying terminals, of a contact member therefor, a stepping-magnet for said member, a controller comprising terminals corresponding to the terminals of said line switching device, a contact-member adapted to sweep over said controller terminals, a stepping magnet therefor, a source of pulsating current, a circuit including said stepping magnets and source of current, means for closing the same, whereby said contact members advance in unison over their respective terminals, and means operated by the controller contact-member when it reaches its terminal representing the desired terminal of the switching device for opening said circuit.

30. The combination with a line switching device carrying line terminals, of a contact-member therefor, a stepping magnet for said member, a controller comprising terminals representing the terminals of said switching device, a contact-member adapted to sweep over said controller terminals, a stepping magnet therefor, a source of current having one pole connected with said member, a key for connecting the other pole to the controller terminal representing the desired line terminal upon the switching device, a source of pulsating current, a circuit including said stepping magnets and source of current, means for closing said circuit, whereby said contact members advance in unison over their respective terminals, a relay in the circuit completed by said controller contact member when it reaches the said terminal, and the member of the switching device reaches the desired line terminal, and means controlled by said relay for opening the circuit of said stepping magnets.

31. The combination with a line switching device carrying line terminals, of a contact member therefor, a stepping magnet for said member, a controller comprising terminals representing terminals of said line switching device, a contact member adapted to sweep over said controller terminals, a stepping magnet for said controller contact-member, a source of current, a conductor connected

- with one pole of said source and with said member, a relay in said conductor, a key comprising plungers and springs adapted to apply current from the other pole of said source to the controller terminal representing the desired line terminal, a source of pulsating current, a circuit including said stepping magnets and source of pulsating current completed by said key when operated, and means operated by said relay when the controller contact-member reaches the controller terminal connected with said source of current for opening the circuit of the stepping magnets.
- 15 32. In a telephone exchange system, the combination with a telephone line extending from a substation to a central office, of a connecting circuit at the central office, a connection-switch for uniting said connecting-circuit with the line, an automatic connector for said connecting-circuit carrying line terminals, a contact-member for said connector, a stepping magnet for said member, a controller comprising terminals representing line terminals, a contact-member adapted to sweep over said terminals, a stepping magnet for said controller contact-member, means for applying pulsating current to said stepping magnets actuated by the operator in setting the controller, and means automatically operated when the controller contact-member reaches its terminal representing the desired line terminal, for cutting off said current.
- 35 33. In a telephone exchange system, the combination with a telephone line extending from a substation to a central office, of a connecting-circuit at the central office, a connection-switch for uniting said connecting-circuit with the line, a line switching device for said connecting circuit carrying line terminals, a contact-member for said device, a stepping magnet for advancing said member over said terminals, a controller comprising terminals representing line terminals, a contact-member adapted to sweep over said controller terminals, a stepping magnet for said member, a conductor connected with said controller contact-member, a relay in said conductor, a source of current, a relay 26 adapted to connect one pole of said source of current with said conductor, a circuit for said relay and an operator's key controlling the same, a key comprising plungers and springs adapted to connect the controller terminal representing the desired line terminal with the other pole of said source, means for applying pulsating current to said stepping magnets controlled jointly by said key and relay 26 when operated, and means operated by said relay in the circuit completed by the controller contact-member when it reaches the controller contact connected with battery for removing pulsating current from the stepping magnets.
34. In a telephone exchange system, the combination with a telephone line extending from a substation to a central office, of a connecting-circuit at the central office, a connection-switch for uniting said connecting-circuit with the line, an automatic connector carrying line terminals, a contact member for said connector a stepping magnet for said member, a controller comprising terminals representing line terminals, a contact member adapted to sweep over said controller terminals, a stepping magnet for said controller contact-member, a conductor connected to said member, a cut-off relay in said conductor, a source of current, a relay 26 adapted to connect one pole of said source of current with said conductor, an operator's key, a locking circuit for relay 26 controlled by said operator's key, a sending key comprising plungers and springs adapted to connect the controller terminal representing the desired line terminal with the other pole of said source, means for applying pulsating current to said stepping magnets controlled jointly by said relay 26 and sending key, whereby said stepping magnets advance their contact members in unison, and means operated by said cut-off relay, when the controller contact-member reaches the controller contact connecting with said source and the connector member reaches the desired line terminal, for removing said pulsating current from the stepping magnets, and for opening the locking circuit of relay 26.
- 40 35. The combination with mechanical line switching mechanism, of sending apparatus adapted to be set to operate said mechanism and connect with a desired line, means for locking said sending apparatus in its operative position, and means automatically operating when said mechanism unites with a desired line for restoring said apparatus.
- 45 36. The combination with an automatic line connector, of digit keys having plungers representing the digits of lines, a relay 26 and circuit therefor, means controlled by said relay and the depression of a plunger representing a line, for operating said connector to connect with said line, a locking bar for maintaining said plunger depressed, a release magnet, a cut-off relay, a circuit therefor completed when said connector unites with the desired line, means controlled by said cut-off relay for opening the circuit of relay 26, and a circuit for said release magnet completed upon the de-energization of relay 26, said release magnet being adapted when operated to move said locking bar and release the depressed plunger.
- 50 37. The combination with a telephone line extending from a substation to a central of-

5 fice, of a connecting-circuit at the central office, a connection-switch for uniting said connecting-circuit with the line, an automatic line switching device carrying line terminals, a contact member for said line switching device arranged to have two movements differing in character, to select a desired terminal, a magnet adapted to give said member one of said movements, a 10 magnet adapted to give said member the other movement, a source of pulsating current, and automatic mechanism adapted to successively complete circuits for said magnets including said source of current, to advance said member to the desired terminals.

38. The combination with a telephone line extending from a substation to a central office, of a connecting-circuit at the central office, a connection-switch for uniting said connecting circuit with the line, an automatic line switching device having vertical rows of terminals and a contact arm forming the terminal of said connecting circuit 20 adapted to be rotated to select a desired row, and moved longitudinally along the terminals of said row, a pair of magnets for operating said arm, and sending apparatus adapted to be set by the operator to operate said magnets to advance said arm to the proper row, and along said row to the desired line terminal.

39. The combination with a telephone line extending from a substation to a central office, of a connecting circuit at the central office, a connection-switch for uniting said connecting-circuit with the line, an automatic line switching device having terminals arranged in groups, a contact-member 35 for said device arranged to have two movements, one from group to group and the other along a desired group, a pair of magnets for imparting said movements to said member, sending keys adapted to be set by the operator, means controlled by said keys for applying pulsating current to one of said magnets to cause said member to select the proper group, means controlled by said keys and automatically operated when said member reaches the proper group for applying said pulsating current to the other magnet to cause said member to move along said row to the desired line terminal, and means automatically operated when said member reaches the desired line terminals, for cutting off said pulsating current.

40. The combination with a telephone line extending from a substation to a central office, of a connecting circuit at the central office, a connection-switch for uniting said connecting-circuit with said line, an automatic line switching device carrying line terminals, a contact-member for said device arranged to have two movements of different character to unite said connecting-cir-

70 cuit with a desired line, a magnet adapted to advance said member through one of said movements, a magnet adapted to advance said member through the other movement, tens and units controllers adapted to be set by the operator to cause said switching device to connect with a desired line, a circuit for the first-mentioned magnet completed by the tens controller when set to advance said member to a position corresponding to 75 the tens digit of the called subscriber's number, means automatically operated when the member has been given said steps for cutting off said tens controller, opening said circuit, and bringing the units controller 80 into operation, a circuit for said other stepping magnet completed by said units controller for advancing said member to the desired line terminal, and means automatically operated when said member reaches 85 the desired line terminal for cutting off said controller and opening said last-mentioned magnet circuit.

41. The combination with telephone lines, of an operator's connecting-circuit, mechanical switching mechanism forming the terminal of said connecting circuit for connecting the same with one of said lines, sending apparatus adapted to be set by the operator to actuate said switching mechanism, a signal associated with said sending apparatus, and automatic means for displaying the same during the use of said sending apparatus.

42. In a semi-automatic telephone exchange system, the combination with a connecting circuit adapted to be united with a calling line, of selector mechanism adapted to extend the circuit to other lines, groups 100 of trunk lines leading to distant offices, each group of trunk lines being represented by 105 a corresponding key before the operator, and automatic sending apparatus arranged to be controlled by said keys, said apparatus being adapted under the control of any office key to cause the selecting mechanism to pick out the group of trunk lines designated by such key, and means associated with said selector mechanism adapted to cause the same to test said trunk lines in rotation and 110 seize the first idle one.

43. In a semi-mechanical telephone exchange system, the combination with selector mechanism, of sender apparatus comprising a set of keys and a series of controller 120 mechanisms adapted to be brought into successive operation to govern successive selecting operations, each controlling mechanism except the last of the series having means actuated automatically upon reaching a 125 point predetermined by a corresponding key or combination of keys for switching the next controlling mechanism of the series into action.

44. In a semi-mechanical telephone ex- 130

change system, the combination with a connecting circuit, of selector mechanisms having busy test apparatus, a visual signal associated with said connecting circuit, and 5 means controlled by said busy test apparatus for operating said visual signal.

45. The combination with a set of keys, of a register mechanism having a terminal connected to each key, a brush cooperating 10 with said terminals, a motor magnet for said brush, circuits governing said motor magnet, switching contacts associated with said register, actuating means for said contacts movable with said register brush, and 15 a selection controller provided with terminals electrically connected to said switching contacts, a brush cooperating with said controller terminals and a motor magnet for said controller brush governed by the 20 dition of said controller terminals.

46. The combination with a set of keys, of a register mechanism having a terminal electrically connected to each key, a brush cooperating with said terminals, a motor magnet 25 for said brush, circuits for governing said motor magnet and including the brush, a register terminal and a key, switching contacts associated with said register, a selection controlling mechanism provided with 30 terminals and with a cooperating brush, a stepping magnet for said mechanism, and controlling circuits for the stepping magnet including the switching contacts, the terminals of said mechanism and its brush.

35 47. A telephone switching system comprising selecting apparatus, a set of decimal digit-keys, a register mechanism having corresponding decimal terminals connected to the keys and a movable brush cooperating 40 therewith, contact mechanism movable with the brush, and a selection controlling mechanism provided with terminals arranged in non-decimal groups.

48. A sender apparatus comprising sets 45 of decimal keys, register mechanism having decimal terminals, a brush cooperating therewith, a motor magnet for the brush and contact devices operated in the movement of the brush, point finder mechanism having non- 50 decimal terminals, a cooperating brush and a motor magnet for the brush, circuits governing the motor magnet of the register and including the keys together with the terminals and brush of said register, and 55 circuits for governing the motor magnet of the point finder and comprising the contact devices and the point finder terminals and brush.

49. The combination with a plurality of 60 central stations, of substation lines extending thereto, trunk lines leading between the central stations, a connecting circuit at a central station, a manually operable switch for connection with the substation lines and 65 having a member furnishing one terminal

of the connecting circuit, an electromechanical station selecting switch adapted to be connected with said circuit, an automatic trunk selecting switch serving to unite said station selecting switch with a trunk line, 70 and means under the control of the station operator for controlling said first-named selecting switch.

50. A switching system for uniting central stations comprising groups of trunk 75 lines leading between the stations, a station selecting switch under the control of an operator at each station and being provided with terminals corresponding to the groups of trunks, and an automatic switch connected to each of said terminals and to each trunk of a corresponding group.

51. The combination with telephone lines and a central station to which they extend, of mechanical switching apparatus for connecting the lines comprising a series of selecting mechanisms, a sender under the control of the operator adapted to be set to cause successive selective movements of the selecting mechanisms, a key under the control of the operator for initially associating said sender and said mechanisms, and means automatically controlled by said sender for disconnecting said sender and said mechanisms at the termination of the control of said mechanisms by said sender.

52. The combination with mechanical switching apparatus, of apparatus adapted to be set by an operator for controlling the switching apparatus, means for associating and dissociating the controlling apparatus and switching apparatus, a connecting circuit and a manually operable switch associated therewith, said switch when operated for obtaining the desired number also effecting connection of said controlling apparatus and switching apparatus, and automatic means for effecting dissociation of 100 said two sets of apparatus.

53. In an exchange system, the combination with telephone lines, of apparatus for switching said lines, controlling apparatus for the switching apparatus, an operator's listening key, and means connected with the key for associating the controlling 110 and switching apparatus substantially as described.

54. The combination with electromechanical switching apparatus, of a source of pulsatory current, electromechanical controlling apparatus for the switching apparatus, and means forming a part of the controlling apparatus for determining the application of the pulsatory current to its own mechanism and that of the switching apparatus.

55. The combination with a central station and telephone lines extending thereto, of an operator's circuit for connecting the lines, an electromechanical switch in the connecting circuit, a source of pulsatory 125 130

current, and controlling apparatus for manipulation by the operator and having portions automatically movable said controlling apparatus serving to apply the pulsatory current both to the electromechanical switch and its own automatically movable portions.

56. The combination with a central station and telephone lines extending thereto, of an operator's circuit for connecting the lines, an electromechanical switch in the connecting circuit, a source of pulsatory current, controlling apparatus for manipulation by the operator, said controlling apparatus serving to apply selective impulses to the electromechanical switch, and means included in the controlling apparatus and operating when selection has been completed by the switch to cut off the pulsatory current, as and for the purposes described.
- 10 57. A telephone exchange system comprising one or more central stations provided with answering jacks, a mechanical switching apparatus having final connecting terminals, telephone lines extending both to said jacks and to the final connecting terminals, a connecting circuit at each central station, said connecting circuit having a plug for cooperation with an answering jack and also including an element of the mechanical switching apparatus, and means operating upon the connection of the mechanical switching apparatus with the busy terminal of a called line for effecting the restoration of said switching apparatus to its 35 normal position.

58. The combination with one or more central stations provided with answering jacks and with selecting switches having a movable connecting member, of telephone lines, each extending both to a jack and to a selector, a relay assisting each selector in the establishment of a connection, said relay being incapable of operation when said selector cooperates with a line which is busy, and means dependent upon the non-energization of the relay for releasing the movable member of the selector.

59. In a telephone exchange system, the combination with a number of operators' connecting circuits, of mechanical line switching mechanism for each connecting circuit adapted to connect said circuit with the desired line, a controller for operating any one of said mechanisms, means for associating said controller with any one of said connecting circuits to operate its individual switching mechanism, and means actuated when said controller is taken for use by one connecting circuit for automatically locking out the other circuits therefrom.

60. In a telephone exchange system, the combination with a number of connecting circuits, of line switching mechanism for each connecting circuit adapted to connect the same with a telephone line, a controller

for operating any one of said mechanisms, means controlled by the operator for associating said controller with any one of said connecting circuits to operate its individual switching mechanism, means automatically actuated when said controller is taken for use by one circuit for locking out the other circuits therefrom, and means automatically actuated when the switching mechanism with which the controller is associated connects its circuit with the desired line, for disconnecting said controller from said connecting circuit and rendering the same accessible to the other connecting circuits.

61. The combination with a plurality of connecting circuits, of switching mechanism associated therewith, a sending device, said circuits being all normally in operative relation to said sending device, and electromagnetic means operated when said sending device is taken for use by one circuit for removing the remaining circuits from operative relation to said sending device.

62. The combination with a plurality of connecting circuits, of switching mechanism associated therewith, a sending device, said circuits being all normally in operative relation to said sending device, automatic means operated when said sending device is taken for use by one circuit for removing the remaining circuits from operative relation to said sending device, and means operated when said sending device has completed its work for restoring said remaining circuits to operative relation to said sending device.

63. The combination with a plurality of connecting circuits, of switching mechanism therefor, a keyboard, electromagnetic means arranged to associate said keyboard with any one of said connecting circuits, and automatic means for locking out the remaining connecting circuits from such keyboard.

64. The combination with a plurality of connecting circuits, of switching mechanism therefor, a controlling mechanism, an operator's key for each connecting circuit for associating said controlling mechanism with its connecting circuit if such mechanism is idle, and means actuated in case one of said keys has tied said controlling mechanism to its connecting circuit for preventing the key of any other cord circuit when operated from connecting said controlling mechanism to its associated connecting circuit.

65. The combination with a plurality of connecting circuits, of selector switching apparatus associated therewith, a calling line, means for placing a connecting circuit in service to connect said line therewith, a sending device and electromagnetic means responsive to said first means for associating said sending device with the connecting circuit first taken for service.

66. The combination with a plurality of connecting circuits, of selector switching ap-

paratus associated therewith, a calling line, switching mechanism for connecting said line with one of said circuits, a sending device, an operator's listening switch, and electromagnetic means governed thereby arranged to associate said sending device with each of said circuits when used.

67. The combination with a plurality of connecting circuits, of selector switching apparatus therefor, a calling line, means for placing a connecting circuit in use to connect said line therewith, a keyboard, and electromagnetic means responsive to said first means for associating said keyboard with any one of said connecting circuits taken for use to operate its selector apparatus.

68. The combination with a plurality of connecting circuits, of selector switching apparatus therefor, a calling line, means for placing a connecting circuit in use to connect said line therewith, a keyboard, and electromagnetic means responsive to said first means for associating said keyboard with the first connecting circuit taken for use to operate its selector apparatus.

69. The combination with a plurality of connecting circuits each terminating at one end in a connecting switch and at the other end in automatic switching apparatus, of means for placing a connecting circuit in service, a sending device, and electromagnetic means responsive to said first means arranged to associate said sending device with such one of said connecting circuits at a point intermediate the ends thereof.

70. The combination with a plurality of connecting circuits each terminating at one end in a connecting switch and at the other end in automatic switching apparatus, of a sending device, an operator's listening key, and electromagnetic means controlled thereby arranged to associate said sending device with each of said circuits when used at a point intermediate the ends thereof.

71. The combination with a plurality of connecting circuits each terminating at one end in a connecting switch and at the other end in automatic switching apparatus, of a sending device, electromagnetic means arranged to associate said sending device with the first one of said circuits taken for use at a point intermediate the ends thereof, and means for locking out other circuits from said sending device.

72. The combination with a plurality of connecting circuits each terminating at one end in a connecting switch and at the other end in automatic switching apparatus, of means for placing a connecting circuit in service, a sending device, and electromagnetic means responsive to said first means for associating said sending device with any one of said connecting circuits taken for use at a point intermediate the ends thereof.

73. The combination with a plurality of connecting circuits each terminating at one end in a connecting switch, of automatic selector apparatus associated with the other end of said connecting circuits, means for placing a connecting circuit in use, a keyboard sender adapted to be set to control the operation of said automatic apparatus, and electromagnetic means arranged to automatically associate said keyboard with anyone of said connecting circuits taken for use at a point intermediate the ends thereof to operate the associated selector switching apparatus.

74. The combination with a plurality of connecting circuits each terminating at one end in a connecting switch, of automatic selector apparatus associated with the other end of said connecting circuits, a keyboard, electromagnetic means arranged to automatically associate said keyboard with the first connecting circuit taken for use at a point intermediate its ends to operate the associated selector switching apparatus, and means actuated when the keyboard is taken for use with one circuit for removing it from operative relation to other circuits.

75. In a telephone exchange system, the combination with a telephone line extending from a substation to a central office, of a connecting circuit at the central office, a manually operated connection switch for uniting said connecting circuit with the line, mechanical line switching mechanism, sending apparatus adapted when set to actuate said line switching mechanism to unite the connecting circuit with a desired telephone line, an operator's listening key for said connecting circuit, and means automatically actuated upon the operation of said listening key for associating said sending apparatus with the connecting circuit.

76. In a telephone exchange system, the combination with a telephone line extending from a substation to a central office, of a connecting circuit at the central office, a manually operated connection switch for uniting said connecting circuit with said line, a sending apparatus, mechanical line switching mechanism, an operator's listening key for said connecting circuit, means automatically actuated upon the operation of said listening key for bringing said sending apparatus into operative relation with said connecting circuit, said sending apparatus when set controlling the operation of said switching mechanism to unite the connecting circuit with a desired telephone line, and means automatically operated when said switching mechanism unites with the desired line for disassociating said sending apparatus from the connecting circuit.

77. In a telephone exchange system, the combination with lines, of a plurality of connecting circuits located at a central office, se-

- 70   1. Lector switching apparatus associated with said circuits, switching mechanism for connecting a calling line with one of said circuits, a sending device at the central office for controlling said apparatus, operator's listening-in switches and means controlled thereby adapted automatically to associate said sending device with any one of said connecting circuits.
- 75   2. In a telephone exchange system, the combination with lines, of a plurality of connecting circuits at a central office, selector switching apparatus associated with said circuits, switching mechanism for connecting a calling line with one of said circuits, a sending device at the central office for controlling said apparatus, an operator's listening set and electromagnetic means automatically operated incident to connecting said set to any one of said circuits for associating said sending device with such connecting circuit.
- 80   3. In a telephone exchange system, the combination with lines, of a plurality of connecting circuits at the central office, automatic switching apparatus associated with said connecting circuits, means for connecting a calling line with any one of said connecting circuits, a sending device at the central office for controlling said apparatus, and automatic means arranged to isolate said sending device for use with any one of said connecting circuits when taken for use and to disconnect the same when the selector switching apparatus has united said connecting circuit with a wanted line.
- 85   4. In a telephone exchange system, the combination with a plurality of connecting circuits at a central office thereof, of switching mechanism associated with said connecting circuits, a sending device at said central office, a listening key associated with each said connecting circuit, and electromagnetic means arranged to associate said sending device with any one of said circuits responsive to the operation of the listening key of such circuit.
- 90   5. In a telephone exchange system, the combination with a plurality of connecting circuits at a central office thereof, switching mechanism associated with said connecting circuits, a sending device at said central office, a listening key associated with each said connecting circuit, and electromagnetic means arranged to associate said sending device with each of said circuits responsive to the operation of the listening key of the circuit to be used.
- 95   6. In a telephone exchange system, the combination with a plurality of connecting circuits at a central office thereof, of switching mechanism associated with said connecting circuits, a sending device at said central office, electromagnetic means arranged to associate said sending device with any one of said circuits, and means for locking out the other circuits from said sending device.
- 100   7. In a telephone exchange system, the combination with a plurality of connecting circuits at a central office thereof, of switching mechanism associated with said connecting circuits, means for placing a connecting circuit in use, a common sending device at said central office, and electromagnetic means responsive to said first means to associate said sending device with such circuit.
- 105   8. In a telephone exchange system, the combination with a plurality of connecting circuits at a central office thereof, of switching mechanism associated with said connecting circuits, a sending device at said central office, a listening key associated with each said connecting circuit, and electromagnetic means arranged to associate said sending device with the first of said circuits, the listening key of which is operated.
- 110   9. In a telephone exchange system, the combination with a plurality of connecting circuits at a central office thereof, of switching mechanism for said connecting circuits, a keyboard at said central office, a listening key for each of said connecting circuits, and electromagnetic means arranged to automatically associate said keyboard with any one of said connecting circuits when the listening key of such circuit is operated, to operate its switching mechanism.
- 115   10. In a telephone exchange system, the combination with a plurality of connecting circuits at a central office thereof, of switching mechanism for said connecting circuits, a keyboard at said central office, a listening key for each of said connecting circuits, and electromagnetic means arranged to automatically associate said keyboard with any one of said connecting circuits when the listening key of such circuit is operated, to operate its switching mechanism.
- 120   11. In a telephone exchange system, the combination with a plurality of connecting circuits at a central office thereof, of switching mechanism for said connecting circuits, a keyboard at said central office, a listening key for each of said connecting circuits, and electromagnetic means arranged to automatically associate said keyboard with any one of said connecting circuits when the listening key of such circuit is operated, to operate its switching mechanism.
- 125   12. In a telephone exchange system, the combination with a plurality of connecting circuits at a central office thereof, of switching mechanism for said connecting circuits, a keyboard at said central office, a listening key for each of said connecting circuits, and electromagnetic means arranged to automatically associate said keyboard with any one of said connecting circuits when the listening key of such circuit is operated, to operate its switching mechanism.
- 130   13. In a telephone exchange system, the combination with a plurality of connecting circuits at a central office thereof, of switching mechanism for said connecting circuits, a keyboard at said central office, and electromagnetic means automatically responsive to said first means to associate said keyboard with any one of said connecting circuits taken for use to operate its switching mechanism.

- circuits at a central office thereof, of a switching mechanism for said connecting circuits, a keyboard at said central office, a listening key for each said connecting circuit, and electromagnetic means arranged to automatically associate said keyboard with the first connecting circuit, the listening key of which is operated, to operate its switching mechanism. 5
- 10 90. The combination with a plurality of connecting circuits, of selector switching apparatus associated therewith, a calling line, switching mechanism for connecting said line with one of said circuits, a sending device, a listening key for each said connecting circuit, and electromagnetic means arranged to associate said sending device with any one of said connecting circuits, the listening key of which is operated. 15
- 20 91. The combination with a plurality of connecting circuits, of selector switching apparatus associated therewith, a calling line, switching mechanism for connecting said line with one of said circuits, a sending device, a listening key for each of said connecting circuits, and electromagnetic means arranged to associate said sending device with each of said circuits when used upon the operation of the listening key of such 25 circuit. 30
92. The combination with a plurality of connecting circuits, of selector switching apparatus associated therewith, a calling line, switching mechanism for connecting said line with one of said connecting circuits, a sending device, a listening key for each of said connecting circuits, and electromagnetic means arranged to associate said sending device with the first one of said circuits, 35 the listening key of which is operated. 40
93. The combination with a plurality of connecting circuits, of selector switching apparatus therefor, a calling line, switch means for connecting said line with one of said 45 connecting circuits, a keyboard, a listening key for each of said connecting circuits, and electromagnetic means arranged to automatically associate said keyboard with any one of said connecting circuits responsive to 50 the operation of its listening key to operate its selector apparatus. 55
94. The combination with a plurality of connecting circuits, of selector switching apparatus therefor, a calling line, switch means for connecting said line with one of said 60 connecting circuits, a keyboard, a listening key for each said connecting circuit, and electromagnetic means arranged to automatically associate said keyboard with the first connecting circuit, the listening key of which is operated, to operate its selector apparatus. 65
95. In a telephone exchange system, the combination with lines, a plurality of connecting circuits at the central office thereof, 70 automatic switching apparatus associated with said connecting circuits, means for connecting a calling line with any one of said connecting circuits, a sending device at said central office for controlling said apparatus, a listening key for each said connecting circuit, and automatic means arranged to associate said sending device with any one of said connecting circuits responsive to the operation of the listening key of said circuit and to disconnect said sending device from said connecting circuit when the selector switching apparatus has united said circuit with a wanted line. 75
96. In a telephone exchange system, the combination with lines, of a plurality of connecting circuits at a central office thereof, selector switching apparatus associated with said circuits, switching mechanism for connecting a calling line with one of said circuits, a sending device at said central office for controlling said apparatus, a listening key for each said connecting circuit, and electromagnetic means arranged to associate said sending device with one of said connecting circuits when its listening key is operated. 80 85
97. In a telephone exchange system, the combination with lines, of a plurality of connecting circuits located at a central office thereof, selector switching apparatus associated with said circuits, switching mechanism for connecting a calling line with one of said circuits, a sending device at said central office for controlling said apparatus, a listening key for each said connecting circuit, and means adapted automatically to associate said sending device with any one of said connecting circuits, the listening key of which is operated. 90 95
98. In a telephone exchange system, the combination with a plurality of operator's connecting circuits, each terminating in a selector, of a sending apparatus, lead-wires extending from said sending apparatus to all the connecting circuits, means for placing a connecting circuit in use, and a switch associated with each connecting circuit and responsive to said first means to bring the selector into connection with said lead-wires, whereby the selector may be controlled by the sending apparatus. 100 110 115
99. The combination with a plurality of operator's connecting circuits, of an automatic sender apparatus, a magnet associated therewith, means controlled by said magnet for making operative said sender apparatus, a circuit for said magnet having multiple branches associated with each connecting circuit, and a switch associated with each connecting circuit for closing the corresponding branch. 120 125
100. In a telephone exchange system, the combination with subscribers' lines, of an operator's connecting circuit having a con- 130

nection switch at one end adapted to unite said connecting circuit with a calling line, a selector adapted to unite said connecting circuit with a line wanted, a sending apparatus adapted to control said selector, automatic sender seizing mechanism adapted to bring said sender apparatus into operative relation to said selector, a key associated with said connecting circuit, and means 10 controlled jointly by said key and said connection switch for actuating said sender seizing mechanism.

101. In a semi-mechanical telephone exchange system, the combination of telephone lines extending from substations to a central office, of selector mechanism at the central office, a connecting circuit adapted to be united with a calling line, a selector adapted to unite the connecting circuit with a line wanted, an automatic sender apparatus adapted to govern the operation of said selector mechanism, an operator's telephone, a listening key associated with said connecting circuit for bringing said telephone into service, and means actuated in the operation of said listening key for associating said sender apparatus with said connecting circuit.

102. In a telephone exchange system, the combination with an operator's cord circuit having an answering plug, a selector adapted to unite said cord circuit with a line wanted, a telephone line having a springjack adapted to receive said answering plug, a relay in a local circuit adapted to be established by said plug when inserted in said springjack, a key associated with said cord circuit, a local circuit, a magnet in said local circuit controlled jointly by said key and said relay a sender apparatus adapted to govern the operation of said selector and means made operative by said magnet for bringing said selector under control of said sending apparatus.

103. The combination with a plurality of operator's connecting circuits each provided with a selector, of a sender, leads from the sender extending in multiple branches to all of said selectors, automatic auxiliary switching mechanism for each selector governing the connection thereof to the sender leads, circuits for initially operating said auxiliary switching mechanism, and means for interrupting said circuits while the sender is in use.

104. The combination with a selector, of a sender adapted to control the same, an operator's connecting circuit, automatic switching apparatus adapted to shift the connections of the selector from the sender to the connecting circuit, and means controlled by the sender in completing its operation for causing such operation of said switching apparatus.

105. In a telephone exchange system, the

combination with operator's connecting circuits each terminating in a selector, of automatic sending apparatus adapted to be set in operation to cause a selector to unite its connecting circuit to a telephone line, means 70 for associating said sending apparatus with a connecting circuit, and means automatically actuated by the sending apparatus in completing its operation adapted to disassociate said sending apparatus from such 75 connecting circuit.

106. The combination with an operator's connecting circuit, of an automatic selector adapted to unite said circuit with a line wanted, a controlling magnet for said selector, a sender, automatic switching apparatus adapted to establish a controlling circuit from the sender to said controlling magnet, and means actuated by the operation of the sender for causing said automatic 85 switching apparatus to open said controlling circuit.

107. In a telephone exchange system, the combination with operator's connecting circuits provided with automatic selectors for 90 extending connections, of a sending apparatus, automatic switching mechanism associated with each selector controlling the connection of said selector to said sending apparatus, and means controlled by each connecting circuit and by the sending apparatus for operating said automatic switching mechanism.

108. In a telephone exchange system, the combination with selectors and a plurality 100 of operators' connecting circuits, of an operator's sending apparatus, means for placing a connecting circuit in use, lead wires extending from said sending apparatus to all the connecting circuits, and a switch associated with each connecting circuit and responsive to said first means, adapted to bring the selector into connection with said lead wires, whereby the selector may be controlled by said sending apparatus.

109. In a telephone exchange system, the combination with an automatic switching device having a movable switch member and sets of terminals adapted to be traversed thereby, certain of said sets of terminals representing ordinary subscribers' lines and other sets representing subscribers' trunk lines, the latter sets being arranged in groups, each set in any such group, except the last set reached by the switch member 115 in traversing the same, having connection of different character from the sets representing subscribers' lines, and testing means associated with the traveling switch member, adapted to respond differently according as 120 the terminals tested are of one class or the other.

110. In a telephone exchange system, an automatic connector having a traveling switch member, sets of terminals represent- 130

ing subscribers' lines and other sets of terminals representing trunk lines, the latter sets being arranged in groups in which each set except the last of any group has distinctive connections different from ordinary lines, in combination with testing means associated with said traveling switch member adapted to respond differently according as the terminals tested are of one class or the other, and mechanism for advancing the switch member, arranged to be brought into service by said testing means in its response to the test of a busy trunk line.

111. In a telephone exchange system, the combination with an automatic connector having a movable switch member and sets of terminals adapted to be traversed thereby, representing subscribers' lines and trunk lines, of a test circuit adapted to be established by said switch member at each set of terminals, a polarized relay in such test circuit, means controlled by said polarized relay in its response to current of a given polarity in said test circuit for advancing said switch member, a marginal relay also in said test circuit adapted in its responsive to prevent the advance of said switch member, busy signal apparatus controlled by said marginal relay, and means controlled in the use of any line for changing the electrical condition of its terminals so as to prevent the operation of said marginal relay when such terminals are tested, the sets of terminals representing trunk lines being arranged in groups, with battery connections for all sets except the last different from the connections of ordinary lines and adapted to cause the operation of said polarized relay to advance the switch member in testing a busy trunk line.

112. In a telephone exchange system, the combination with a line switching device carrying line terminals and a group of trunk terminals, of a moving contact member for said switching device, automatic means for advancing said member to any of said line terminals or the first trunk terminal of said group, means, actuated in case said first trunk is busy, for continuing the advance of said member to a terminal of an idle trunk line, and means automatically operated responsive to the selection of said idle line for sending ringing current over said line.

113. In a telephone exchange, the combination with a telephone line extending from a substation to a central office, of link conductors at the central office, a connection switch for uniting said link conductors to the line in response to a call, a line switching device carrying stationary line terminals and trunk terminals, a contact member for said switching device forming movable terminals for said link conductors and adapted to sweep over said stationary terminals, automatic mechanism for directively advanc-

ing the contact member to the terminals of the first trunk, automatic means actuated in case said first trunk line is busy for continuing the operation of said advancing means until an idle trunk line is reached, and means automatically operated responsive to the selection of said idle line for sending ringing current therover.

114. In a telephone exchange system having certain lines thereof terminating in a sub-exchange, the combination with a line switching device, of trunk lines extending to said sub-exchange and terminating at said switching device, a telephone line, a movable contact member for said device in which said line terminates, automatic means for operating said member to select an idle trunk line, a source of ringing current, and means automatically operated when said contact member connects with an idle trunk line for connecting said ringing current therewith.

115. In a telephone exchange, the combination with a line switching device at the central office, of a second exchange, trunk lines leading from said exchange to the terminals on said switching device, a contact member adapted to sweep over said terminals, mechanism for advancing said member to the terminals of the first trunk line, means automatically operated in case said line is busy for advancing the member to the next terminal, and so on until an idle line is found, and means automatically actuated upon the connection of said contact member with the terminals of an idle line for applying ringing current to said line.

116. In a telephone exchange, the combination with a telephone line extending from a substation to a central office, of link conductors at the central office, a connection switch for uniting said link conductors with a line in response to a call, a line switching device carrying terminals of other telephone lines, a private branch exchange, trunk lines leading from said exchange to terminals on said switching device, a contact member adapted to sweep over said terminals, said member being adapted to be connected with said link conductors, automatically operated mechanism adapted to be set manually to advance said member to the terminals of a desired line, said mechanism being adapted to advance said member to the terminals of the first trunk line leading to the private branch exchange, mechanism automatically operated in case said first trunk line is busy for advancing the contact member to the terminals of the next trunk line, and so on until an idle trunk line is reached, and mechanism operated when connection is made with an idle trunk line for applying ringing current thereto.

117. In a telephone exchange, the combination with a connector at the central office,

- of trunk lines leading to terminals upon the connector, a contact member adapted to be advanced to the terminals of the first trunk line, a pair of relays in a circuit completed 5 when the contact member makes connection with terminals of said trunk line, one of said relays responding and the other being unresponsive if such line is busy, mechanism actuated upon the response of the first mentioned of said relays and the quiescence of the second to advance the contact member to the terminals of the next trunk line, and from terminal to terminal until an idle trunk line is reached.
118. In a telephone exchange system, the combination with a line switching device at the central office, of a movable test brush therefor, a series of trunk lines leading to stationary terminals upon said device, each 20 trunk line having a test terminal connected with a source of current, the polarity of which is the same for all but the last one in the series, that being of opposite polarity, a pair of relays included in a circuit completed when the test brush engages the test terminal of the first trunk line, one only of said relays responding to the flow of current in said circuit in case such line is busy, mechanism made operative by this condition 25 of the relays to cause the advance of said test brush from terminal to terminal until an idle or the last trunk line in a series is reached, said test brush in engaging the last terminal completing the circuit for current 30 of opposite polarity through said pair of relays, neither of which will operate however if said last trunk line is busy, and mechanism actuated by this quiescent condition of the relays to return the switching device 35 to its normal condition.
119. In a telephone exchange system, the combination with a telephone line extending from a substation to a central office, of a connecting circuit at the central office, a connection switch for uniting the connecting 40 circuit with said telephone line, a line switching device carrying line terminals, trunk lines leading to terminals of said switching device, a contact member for said device, controlling mechanism adapted to advance 45 said contact member to the terminals of the first trunk line, mechanism actuated in case said trunk line is busy, for advancing said member to the next trunk line terminals, and so on until an idle trunk line is reached, mechanism actuated in case all of said trunk lines are busy for applying a busy signal to the connecting circuit, and mechanism simultaneously operated adapted to release the 50 contact member and permit the same to return to normal condition.
120. In a telephone exchange system, the combination with a line switching device, of trunk lines having terminals upon said device, a movable contact member for said 55 device, automatic means for moving said contact member over said trunk terminals, a busy signal associated with said device, means actuated in case all of said lines are busy for operating said busy signal, and means, actuated in case all of said trunk lines are busy, for releasing said member.
121. In a telephone exchange system, the combination with a line switching device, of a group of trunk lines having terminals upon said device, a movable contact member for said device, sending apparatus for advancing said member to the terminals of the first trunk of said group, and means for automatically moving said member over said trunk terminals until an idle trunk line is reached, a busy signal associated with said device, means actuated in case all said trunk lines are busy, and when the contact member reaches the last trunk terminal, for operating said busy signal, and means for restoring said member to normal position, actuated in case all of said lines are busy.
122. In a telephone exchange system, the combination with a telephone line extending from a substation to a central office, of a connecting circuit at the central office, a connection switch for uniting said connecting circuit with the telephone line, a line switching device carrying terminals for lines in the exchange, trunk lines leading to terminals of said device, a contact member for said mechanism adapted to sweep over said terminals to unite said connecting circuit with said terminals, automatically operated mechanism for advancing said member over said terminals and over said trunk terminals until an idle trunk line is reached, a busy signal, and means actuated in case all of said trunk lines are busy, for applying said busy signal to said connecting circuit, and for causing the return to normal of said contact member.
123. In a telephone system, the combination with a telephone line extending from a substation to a central office, of an operator's connecting circuit at the central office, a manually operated connection switch at the central office for uniting one end of said connecting circuit with the line, an automatic connector, automatic mechanism for operating said connector to unite said connecting circuit with a called line, a private branch exchange, trunk lines leading from said exchange to said connector, and means for causing said connector to automatically select an idle trunk line and unite said connecting circuit therewith.
124. In a telephone system, the combination with a telephone line extending from a substation to a central office, of an operator's connecting circuit at the central office, a manually operated connection switch at the central office for uniting one end of said connecting circuit with the line, an auto-

- matic connector, automatic mechanism for operating said connector to unite said connecting circuit with a called line, a private branch exchange, trunk lines leading from said exchange to said connector, means for causing said connector to automatically select an idle trunk line and unite said connecting circuit therewith, a busy signal, and means automatically operated in case said 10 trunk lines are all busy, for applying said busy signal to the connecting circuit.
125. In a telephone exchange system, the combination with a line switching device, of trunk lines leading to terminals thereon, 15 a contact member for said device adapted to be advanced to the terminals of the first trunk line, a pair of relays, a circuit for said relays completed by the contact member in connecting with the terminals of said 20 line, a shunt about one of said relays to prevent its operation, established at another device already connected with said line, the other relay being responsive, and mechanism actuated upon the response of the second 25 mentioned relay and non-response of the first, for advancing said member to the terminals of the next trunk line.
126. In a telephone exchange system, the combination with a line switching device, 30 of a contact therefor, a series of trunk lines leading to terminals upon said device, each trunk line having a test terminal connected with a source of current, the polarity of which is the same for all but the last one 35 in the series, that being of opposite polarity, a pair of relays included in a circuit completed when the test brush of said member engages the test terminal of a trunk line, one of said relays responding and the other 40 being unresponsive in case such line is busy, mechanism operated by the energization of the first mentioned relay and quiescence of the second to advance said member to the terminals of the next trunk line and from 45 terminal to terminal until an idle trunk line is reached, the test brush of said contact member in engaging the test terminal of the last trunk line completing a circuit for current of opposite polarity through 50 said relays, both said relays being quiescent in case said last trunk line is busy, and a busy signal actuated by said relays when quiescent.
127. The combination with a line switching device, of trunk lines leading to terminals upon said device, a contact member adapted to sweep over said terminals, a source of current of one polarity connected with the terminals of all the trunk lines except 55 one, a source of current of opposite polarity connected with the latter trunk line terminal, mechanism, actuated when the contact member engages the terminal of a busy trunk line connected with said current of the first-named polarity, for advancing said 60 member to another trunk line terminal, and means, responsive when the member engages the trunk line terminal connected with said source of opposite polarity, if such trunk line is in use, adapted to restore said member. 70
128. The combination with a line switching device, of trunk lines leading to terminals upon said device, a contact member adapted to sweep over said terminals, a source of current of one polarity connected with the terminals of all the trunk lines except one, a source of current of opposite polarity connected with the latter trunk line terminal, mechanism, actuated when the contact member engages the terminal of a busy trunk line connected with said current of the first-named polarity, for advancing said member to another trunk line terminal, and busy signal apparatus controlled, when the contact member reaches said latter trunk terminal, if such line is in use, by current of second-named polarity. 75
129. The combination with a line switching device, of trunk lines leading to terminals upon said device, a source of current of one polarity connected with all said trunk terminals except the last, a source of current of opposite polarity connected with the last trunk line terminal, a contact member for said device, mechanism adapted to advance said member to the first trunk line terminal, mechanism responsive when the member engages said terminal, if the trunk line is busy, to current of said first-named polarity to advance said member to the terminal of the next trunk line, and from terminal to terminal until an idle trunk line is reached, and means, responsive when the member engages the last trunk terminal, if such line is busy, to current from said second named source, adapted to restore said member. 80
130. The combination with a line switching device, of trunk lines leading to terminals upon said device, a source of current of one polarity connected with all said trunk terminals except the last, a source of current of opposite polarity connected with the last trunk line terminal, a contact member for said device, mechanism adapted to advance said member to the first trunk line terminal, mechanism responsive when the member engages said terminal, if the trunk line is busy, to current of said first-named polarity to advance said member to the terminal of the next trunk line, and from terminal to terminal until an idle trunk line is reached, a busy signal apparatus associated with said switching device, and means, responsive, when the member engages the last trunk line and the same is busy, to current from said second-named source, adapted to operate said busy signal apparatus and restore said contact member. 85
131. The combination with a line switch- 130

ing device, of trunk lines leading to terminals upon said device, a source of current of one polarity connected with all said trunk line terminals except the last, a source of current of opposite polarity connected with said last trunk line terminal, a contact member for said device, a normally discontinuous talking circuit connected with said member, means for advancing said member to the terminal of the first trunk line, a pair of relays, a circuit for said relays completed by said member in engaging said first terminal and each trunk line terminal, said circuit including the source of current connected with said terminal, one of said relays being polarized to respond only to current of the first-named polarity, means for preventing the operation of the second relay, if said first trunk line is busy, means controlled jointly by the operation of the first relay and the quiescence of the second for advancing said member to the next trunk line terminal, and from terminal to terminal until an idle trunk line is found, the contact member in engaging the last trunk line terminal effecting the quiescence of both relays, in case said last trunk line is busy, means actuated upon the quiescence of both said relays for restoring said member to normal condition, and means controlled by the second of said relays when energized for completing the continuity of said talking circuit.

132. The combination with a line switching device, of trunk lines leading to terminals upon said device, a source of current of one polarity connected with all of said trunk line terminals except the last, a source of current of opposite polarity connected with said last trunk line terminal, a contact member for the switching device adapted to be advanced to the terminal of the first trunk line, a normally discontinuous talking circuit connected with said member, a marginal relay and a polarized relay responsive only to current of said first-named polarity, a circuit for said relays completed by said member engaging said first terminal and each trunk line terminal, said circuit including the source of current connected with said terminal, a short established about marginal relay to prevent its operation in case the first trunk line is busy, polarized relay responding, a stepping magnet for said member, a circuit for said magnet completed upon the quiescence of the first relay and the energization of the second, whereby said magnet advances the member to the next trunk line terminal, and from terminal to terminal until an idle trunk line is reached, both relays being inert when the contact member engages the last trunk line terminal, if such trunk line is in use, busy signal apparatus associated with the switching device, a circuit to operate the same completed upon the quiescence of both said

relays, and means operated by the marginal relay when energized for completing the continuity of said talking circuit.

133. The combination with a line switching device, of telephone lines and a group of trunk lines leading to terminals upon said device, a contact member adapted to sweep over said terminals, a source of current of one polarity connected with said telephone line terminals and with the last of said trunk terminals, a source of current of opposite polarity connected with the remaining trunk line terminals, mechanism, responsive, when the contact member engages the first trunk terminal, if such line is busy, to current of said second-named polarity, adapted to advance said member to the next trunk terminal, and from terminal to terminal until an idle trunk line is reached, busy-signal apparatus associated with said switching device, and means responsive when said member engages the terminal of a busy telephone line or the last trunk line, if such trunk line is busy, to current of the first-named polarity, adapted to operate said busy signal apparatus and restore said member to normal condition.

134. In a telephone system, the combination of a plurality of telephone lines running to the same substation, telephones on said lines, an automatic switch provided with means for extending connection to any of said lines, automatic means for causing the operation of said switch to select the first idle one of said lines, means automatically operated responsive to the selection of said idle line for sending ringing current over said line, a common battery, and relays allotted to said switch and controlling the flow of talking current from said battery to the called telephone line.

135. The combination with a telephone switching mechanism provided with transmission line terminals and two groups of testing line terminals of substation lines having third conductors connected successively to one group of test terminals, and groups of trunks with their third conductors connected to the other group of test terminals but with the final trunk of each trunk group joined to the group of terminals with the substation lines.

136. In a telephone connecting apparatus, the combination with switching mechanism provided with a plurality of groups of terminals and movable contact members cooperative therewith, of controlling means connected to one group of terminals whereby successive tests of busy terminals are secured, and means connected to another group of terminals for governing the restoration of the movable contact members to their normal position upon their cooperation with a busy terminal of said second mentioned group.

137. In a telephone exchange system, the combination with a selector and motor mechanism therefor, of lines terminating in said selector, all of said lines being used for conversational purposes, some of said lines being arranged in groups, a test terminal associated with each of said lines, a test circuit successively including said test terminals during the movement of said selector, a relay in said test circuit, means associated with the test terminals of the lines of a group other than the last line of such group to energize said relay, and means associated with the test terminals of the last line of a group to deenergize said relay. 10
138. In a telephone exchange system, the combination with single lines to subscribers' stations and one or more groups of lines to a single subscriber's station, of automatic switching means for interconnecting subscribers' lines, a ringing generator, a busy signal appliance, a test relay having an armature which in one position permits ringing current to be applied to a called subscriber's line and in another position allows a busy tone to be transmitted to the calling subscriber's line, and another relay associated with said test relay serving to prevent the sending of a busy signal until the last line of a group of lines leading to the same subscriber's station has been tested. 20
139. In a telephone exchange system, the combination with single lines to subscribers' stations and one or more groups of lines to a single subscriber's station, of automatic switching means for interconnecting the subscribers' lines, a ringing generator, a busy signal appliance, a test means which controls the application of ringing current or busy tone to the called and calling subscribers' lines respectively, and means associated with said testing means made effective only when lines of a group to a single subscriber's station are being tested to prevent the sending of a busy signal until the last line of the group has been tested. 30
140. The combination with a line switching device, of a contact member therefor, a controller adapted to be set to operate with said member to determine the advance thereof, operating magnets for said member and controller, a relay, means for applying pulsating currents to said switch magnet and said relay, and a circuit for said controller operating magnet controlled by said relay whereby said magnets are caused to operate one after the other. 40
141. The combination with a line switching device, of a contact member therefor, a stepping magnet for said member, a circuit for said magnet, a controller adapted to be set to determine the advance of said member, an operating magnet for said controller, a source of pulsating current, automatic means actuated by said controller for applying said current to said stepping magnet circuit, a relay in said circuit responsive to current pulsations, a circuit for said controller operating magnet made and broken by said relay; whereby said stepping magnet and operating magnet operate one after the other, a relay adapted to disconnect said source of pulsating current from said stepping magnet circuit, and a circuit for said relay completed when the contact member is advanced a predetermined distance by the controller operating with said member. 50
142. The combination with a line switching device, of a contact member therefor, a stepping magnet and its circuit for said member, a controller comprising terminals corresponding to the terminals of said line switching device over which said contact member moves, a contact member for the controller adapted to sweep over its terminals, a source of current having one pole connected with said controller member, a key for connecting one of such controller terminals corresponding to the terminal of the line switching device with which connection is desired to the other pole of said source, a stepping magnet for said controller member, a pulsator, means actuated upon the operation of said key for applying the same to the circuit of the stepping magnet of said line switching device to make and break the circuit of said magnet, a relay in said circuit responsive to current waves from said pulsator, a circuit for the controller stepping magnet made and broken by said relay, whereby said stepping magnets operate one after the other, a relay connected with said controller member and energized when the same reaches its predetermined terminal adapted to open the circuit of the stepping magnet of the line switching device. 60
143. In a calling apparatus, a series of keys, contact springs for each key operated by the manipulation of their respective keys. connections from the springs of different keys to a corresponding series of terminals, a contact maker adapted to be moved over said terminals, a motor for so moving it, and automatically operating means for stopping said motor when said contact maker engages a terminal corresponding to the operated springs of a manipulated key. 70
144. In a calling apparatus, a series of keys, contact springs for each key, a corresponding series of contact pins, connections from the different springs to corresponding pins, a contact maker adapted to be moved over said pins, a motor for so moving it, and means for automatically stopping said motor when said contact maker engages a pin connected to a spring moved by a key. 80
145. A step-by-step impulse-sending de- 90

- vice provided with a single group of keys, a step-by-step automatic switch adapted to be connected to said impulse sending device, a driving magnet for said step-by-step automatic switch, means controlled by the operation of one of said keys for causing said impulse sending device to step forward, and means for transmitting impulses to said motor magnet to cause said automatic switch 10 to take a number of steps equal in number to the steps taken by said impulse sending device, and means for releasing said impulse sending device without affecting the operative position of said automatic switch.
146. In a telephone system, a plurality of operators' link circuits, a calling device associated with said link circuits, key controlled means for connecting said calling device to one of said link circuits, and means 20 for preventing the said calling device from being connected to another of said link circuits while connected to the said first link circuit.
147. In a telephone system, a calling line, 25 a called line, means including an operator's cord and automatic switching apparatus for connecting the two lines, and a signal for indicating when the called line is busy, said signal being controlled over two sides of the 30 talking circuit in series.
148. In a telephone system, a calling line and a called line, means for connecting said lines comprising a cord circuit and a trunk line terminating in an automatic switch, a 35 signal in the cord circuit, and means actuated when the called line is busy for controlling the operation of said signal over the two talking conductors of said trunk line in series.
149. In a telephone system, an originating office, a terminating office, subscribers' lines terminating therein, a cord circuit at said originating office and selector switches at 40 said terminating office for connecting subscribers' lines, a two-conductor trunk circuit extending between said offices, a supervisory relay in said cord circuit, a lamp under the control of said relay, a resistance in said 45 trunk circuit at said terminating office, and means actuated when the desired line is busy for intermittently shunting said resistance whereby said supervisory relay is operated to flash said lamp to inform the operator 50 that the desired line is busy.
150. In a telephone system, an originating office, a terminating office, subscribers' lines terminating therein, a cord circuit at said originating office and selector switches at 55 said terminating office for connecting subscribers' lines, a two-conductor trunk circuit extending between said offices, a supervisory relay in said cord circuit, a lamp under the control of said relay, a resistance in said 60 trunk circuit at said terminating office, a relay for shunting said resistance, and means actuated when the desired line is busy for intermittently shunting said resistance whereby said supervisory relay is operated to flash said lamp to inform the operator that the desired line is busy.
151. In a telephone system, an originating office, a terminating office, subscribers' lines terminating therein, a cord circuit at said originating office and selector switches at 65 said terminating office for connecting subscribers' lines, a two-conductor trunk circuit extending between said offices, a supervisory relay in said cord circuit, a lamp under the control of said relay, a resistance in said 70 trunk circuit at said terminating office, means actuated when the called subscriber responds for shunting said resistance whereby said supervisory relay responds to extinguish said lamp, and means actuated when the desired line is busy for intermittently shunting said resistance whereby said supervisory relay responds to flash said lamp.
152. In a telephone system, an originating office, a terminating office, subscribers' lines terminating therein, a cord circuit at said 75 originating office and selector switches at said terminating office for connecting subscribers' lines, a two-conductor trunk circuit extending between said offices, a supervisory relay in said cord circuit, a lamp under the 80 control of said relay, a resistance in said trunk circuit at said terminating office, a relay for shunting said resistance, a circuit for said lamp effective upon the response of the called subscriber whereby said resistance is shunted to cause the response of said supervisory relay and the extinguishment of said lamp, and a second circuit for said second 85 relay effective when the desired line is busy for causing the intermittent shunting of said 90 resistance and the consequent flashing of said lamp.
153. In a connective system, a tri-headed trunk connecting selectively to calling lines, operators' equipments and wanted lines at 95 its three heads respectively, substantially as described.
154. In a connective system, a tri-headed trunk connecting selectively to calling lines, operators' equipments and wanted lines at 100 its three heads respectively, the connection with wanted lines being in response to control from the connected operator's equipment, and the connection of the operator's equipment operating to disconnect the operator's equipment from the trunk immediately subsequent to the completion of the connection of the trunk with the wanted line, substantially as described.
155. In a connective system, a tri-headed 105 trunk connecting selectively to calling lines, operators' equipments and wanted lines at its three heads respectively, the connection with wanted lines being in response to control from the connected operator's equipment.

ment, telephone equipments whereby the operator may receive an order from a subscriber upon the connected calling line, and the connection of the operator's equipment operating to disconnect the operator's equipment from the trunk immediately subsequent to the completion of the connection of the

trunk with the wanted line, substantially as described.

In witness whereof, we hereunto subscribe our names this 20th day of September, A. D. 1906.

JAMES L. McQUARRIE.
ALBERT M. BULLARD.
